Specification of Letters Patent. Patented Feb. 13, 1915.

Application filed October 20, 1998. Serial No. 10/000,000

Environ Biol Fish (2007) 80:63–67

Be it known that I, Joseph D. Laramie,
a citizen of the United States, residing at
New Orleans, in the parish of Orleans and
State of Louisiana, have invented and
perfected improvements in Cigar Machines of
which the following is a specification:

My division relates to signs in which the main object of the same being to give all the operators necessary to the exact type of a word, but signs need be given to only specified, the same point, conjugated with words after to effect the different signs to which necessary for proper action will be given.

A further object of the invention is to simplify and improve the construction of the different operative parts of the machine, so which go to make up the complete machine.

Other subjects taught abroad.

The invention consists of a gun-shaped bench-forming mechanism, a rotatable wrap-around applying mechanism, and means for automatically delivering the bench, as these are formed, from the bench-forming to the wrap-around applying mechanism.

The invention also consists of means for 20 generating and sloping the fill of columnar units for delivering the same upon a ladder and means for automatically severing the protruding ends of the fill at the

The invention also consists of a hand
waking table having a pocket therein and
said pocket enclosing theron a pair of rollers
and which said belt passes out of said
pocket, means for automatically retarding said
40 belt so as to roll said belt at a pre-deter-
mined rate, means for automatically
the other end of said pocket, means for
shaped condition onto the blades and said
belt and forcing the same down into said
45 pocket, forming a fold in said belt, and
means for automatically retarding said
belt so as to elevate the filler from said pocket into
contact with said curved surface, and to
simultaneously roll the belt thereon and
50 increase the tension of said belt to contract
and shape the lunch being formed.

The invention also consists of a reciprocating filter table having a reservoir therein, lunch-making mechanism comprising an oscillating table having a pocket at one end

thereof and a branch holder into which the longitudinal branches are fastened at the opposite end thereof, a branch connector made up of a series of rings or pegs, and means for firmly connecting the rings to the filter to hold the longitudinal branches in the filter tube into the proper position supporting the filter and for connecting the longitudinal branches and branch holder to the ends of the filter tube respectively of said filter.

the number of subjects in the previous study. In reporting this study, the term "sample" is used in its conventional definition to refer to the entire group of subjects, as opposed to the term "sample" in the original study.

the potential user consists of a branch bank or a stockholder made up of a series of companies organized for the business, notwithstanding the fact that it makes no record for said receptacle, and the same immediately opening one or more safe deposit boxes for attorney or other purposes, is liable from the inception of such record boxes for maintaining and preserving the same open and free while such boxes are being used, and failing to do so, gives all the right up or rights of the user. The attorney, in recording his name at the receptacle where his safe deposit box is, and causes for his signature, failing to do so, or in any other way failing to do so, is liable.

The harpoon also consists of a branch-
marked for some time the magazines from the
lance, carrying on, following the lance to
the work, an armature consisting of the same
consisting of a long straight blade for clip-
ping the protruding ends of the lance, in one
of said lance ends and longitudinally to the straight
lance, which is already provided for engaging
over the anterior part of the lance.

The invention also consists of a cluster of weapons carrying rolls, a wrapper-carrier rotatable therewith means for cutting and delivering a wrapper upon said carrier, means for raising and lowering the same, means for respecting a variable speed of movement by the wrapper on said carrier toward said rolls, means for moving said carrier longitudinally of said rolls and means for varying the angle at which said carrier lies to said rolls for changing the angle of presentation of the wrapper to the barbs.

The invention also consists of means for 110

applying tension and friction to, and for stretching and removing the creases from, the wrapper, as it is delivered to the bunch.

The invention also consists of a cluster 5 of wrapper-applying rolls, means for delivering a wrapper thereto, a spring tucking needle adapted to be moved to a point above the wrapper and then automatically released to force the wrapper down into contact with the bunch within said rolls, means for automatically withdrawing said needle longitudinally from the bunch and wrapper after more than one complete revolution of the same has been made, and 10 means for automatically re-inserting said needle into the center of the bunch at the tuck end thereof.

The invention also consists in means for automatically cutting the end of the wrap- 20 per as it is being wound upon the head end of the bunch, so as to make the same exactly fit when wound thereon without the formation of projecting portions.

The invention also consists in a rotary 25 tip-shaping-and-polishing cup adapted to be moved back and forth into engagement with the head or tip end of the cigar after the wrapper has been applied thereto.

The invention also consists in novel means 30 for supporting the bunch after the wrapper- applying rolls have separated from each other and for cutting the same at the tuck end.

The invention also consists in certain 35 novel features of construction, combinations of parts, and arrangements of instrumentalities which will be hereinafter more fully described and claimed.

In the drawings forming part of this 40 specification, Figure 1 is a plan view of a cigar machine constructed in accordance with my invention, that portion of the same containing the wrapper-cutting device being broken away. Fig. 2 is a side elevation of

45 the same. Fig. 3 is a vertical longitudinal section of the same partly broken away at one end, the section extending through the center of the bunch conveyor and through the reciprocating bunch-ejecting plungers.

50 Fig. 4 is a vertical section of the reciprocating filler table and the oscillating bunch making mechanism, showing the latter in the position of completing the making of a bunch. Fig. 5 is a detail side elevation of one end of the filler table, the bracket on which the same is mounted and the pivoted guard cooperating therewith. Fig. 6 is an end view of the same showing in elevation the rollers by which the bunch is formed.

55 Fig. 7 is a transverse section of the filler table taken through the filler receptacles therein. Fig. 8 is a detail perspective view of the oscillating bunch forming table. Fig. 9 is a similar view of the pivoted slings carrying frame thereof. Fig. 10 is an end

view of the bunch conveyor and shaper, showing the lids or covers of the bunch-containing cups or receptacles carried thereby, closed, with one of the same in the position it assumes just prior to being opened a portion of the chain of receptacles being removed to show the sprocket wheels. Fig. 11 is a similar view, showing the cover of one of the cups or receptacles carried by said conveyor in its open position, and showing the drying case about which the conveyor moves, in cross section. Fig. 12 is a detail view of the gear for operating the locking and lock-releasing mechanism for the covers of the cups or receptacles carried by the bunch conveyor. Fig. 13 is a detail view showing the lock for one of said covers in the act of being released. Fig. 14 is a similar view showing one of said lids or covers in the act of being locked. Fig. 15 is a detail view, in elevation, of the reciprocating slides for opening and closing the lids or covers of the filler receptacles carried by said conveyor, and the actuating means therefor. Fig. 16 is a detail view, in longitudinal section, of the heating and drying case around which the bunch carrier passes. Fig. 17 is a plan view of the bunch transfer for elevating the bunches from the bunch conveyor and carrying the same to the wrapper-applying mechanism, the same being shown in the act of clipping the projecting ends of the bunch in one of the cups or receptacles of said conveyor and of engaging said bunch for clamping it. Fig. 18 is a sectional view of a portion of the same showing one of the bunch-engaging needles and the means for adjusting the same. Fig. 19 is a sectional view on the line 19-19 of Fig. 17. Fig. 20 is a detail sectional view on the line 20-20 of Fig. 19. Fig. 21 is a perspective view of the bunch carrier, showing the internally movable needle carrying arm. Fig. 22 is a transverse section of a portion of the machine, the section being taken through the center of the cluster of wrapper-applying rolls, through the tucking needle and through the rotating head-polishing cup. Fig. 23 is a detail view partly in longitudinal section, showing the tucking needle raised, in position to engage the projecting end of the wrapper to force the same down into engagement with the bunch. Figs. 24, 25 and 26 are diagrammatic views showing various positions of the wrapper as it is being applied to the bunch. Fig. 27 is a detail perspective view of the longitudinally movable sleeve and the forked lever for raising and lowering the tucking needle. Fig. 28 is an elevation of the jaws to which the ends of the wrapper-applying rolls at the head end of the slings are connected, this view showing said jaws in their closed position and the cutting mechanism for the head end of the

the wrapper in operation. Fig. 29 is a similar view of the same showing the jaws separated and the cutting mechanism for the head end of the wrapper out of operation. Fig. 30 is a detail perspective view of the reciprocating slide which carries one of the cutters for the head end of the wrapper. Fig. 31 is a similar view, of the rocking bracket on which said slide is mounted, the same carrying the other cutter for the head end of the wrapper. Fig. 32 is a detail view in elevation of the cutter for the tuck end of the cigar. Fig. 33 is a detail view of the gripper for the finished cigar, showing the type therein for branding the cigar. Fig. 34 is a detail view, showing in end elevation, the operating mechanism for the reciprocating slide which carries one of the cutters for the head end of the wrapper. Fig. 35 is a similar view, showing the same in side elevation. Fig. 36 is a longitudinal section of the rocking bracket on which said slide is mounted. Fig. 37 is a view similar to Fig. 28 showing the jaws to which the wrapper-applying rolls at the tuck end of the cigar are connected. Fig. 38 is a sectional plan view of the jaws at the head end of the cigar. Fig. 39 is a detail view of one of the wrapper applying rolls. Fig. 40 is an elevation of the jaws to which the wrapper-applying rolls at the head end of the cigar are connected, the said view illustrating a modified construction of cutter. Fig. 41 is a detail plan view of the construction shown in Fig. 40. Fig. 42 is a sectional view taken longitudinally of the machine, the section extending longitudinally through the wrapper carrier and transversely through the wrapper-applying rolls. Fig. 43 is a transverse section through the suction box of the wrapper carrier. Fig. 44 is a plan view of the reciprocating table on which the wrapper carrier frame is pivotally mounted, showing the means for varying the angle of presentation of the wrapper carrier to the bunch. Fig. 45 is a similar view of the same, shown detached from the cooperating parts. Fig. 46 is a bottom plan view of the pivotal end of the wrapper carrier supporting frame. Figs. 47 and 48 are perspective views of the two parts of the frame or casing of the wrapper carrier. Fig. 49 is a plan view of the wrapper cutting die and that portion of the main frame in which the same is mounted. Fig. 50 is a vertical section of said die, of the revolving roller or wrapper-transferring device cooperating therewith, the operating means for said roller, and the means for varying the suction in said roller and in said die. Fig. 51 is a sectional view of a portion of the wrapper cutting die. Fig. 52 is a view of the treadle for operating the valve which controls the suction of said die, and Fig. 53 is a view of a

foot-controlled mechanism for throwing the machine into and out of operation.

Like reference numerals indicate like parts in the different views.

The main frame of the machine may be of any construction suitable for the support of the operative parts. Mounted in said frame and extending transversely thereof is a main drive shaft 1 having a driving gear 2 on one end thereof and a disk or cam wheel 3 on its opposite end. Also mounted in said frame, and extending transversely thereof parallel to the shaft 1 is a counter shaft 4, the same being provided with a gear wheel 5 on one end and a gear wheel 6 on the opposite end. The teeth of the gear wheel 5 mesh with those of the gear wheel 2 and through the latter the motion of the main drive shaft 1 is transmitted to the counter shaft 4. All the operative parts of the device are driven directly or indirectly from the shafts 1 and 4 so that when the main drive shaft 1 is thrown out of operation the whole machine will be stopped. Power from any suitable source is transmitted to the main drive shaft 1 through a belt wheel or pulley 7, loosely mounted on the outer end of said shaft but having a clutch connection therewith. The clutch between the pulley 7 and the drive shaft comprises a longitudinally movable sleeve 8 keyed to the shaft 1 and having a cone-shaped end 9, and the pivoted arms 10. The said arms 10 are pivoted in the opposite ends of a bracket 11 secured to the shaft 1 adjacent to the pulley 7, one end of each of said arms being adapted to be engaged by the cone-shaped end 9 of the sleeve 8 and the other end of each of said arms being adapted to engage the inner surface of the pulley 7. For throwing the sleeve 8 which constitutes one member of the clutch into and out of operative relation to the arms 10 which constitute the other member of the clutch, I provide a treadle 12 mounted within convenient reach of the operator and connected through a rod or pitman 13 with a bell crank lever 14 clearly shown in Fig. 52. The latter lever is fulcrumed to a fixed part of the frame and the upper arm thereof is provided with a fork 15 which straddles or straibaces the sleeve 8. The branches of said fork are provided with inwardly extending pins or projections 16, which fit within an annular groove 17 in the periphery of said sleeve. Connected with the upper arm of the bell crank lever is a spring 18 which serves to retract said lever and normally maintain the sleeve 8 out of contact with the arms 10. By this construction it will be observed that by depressing the forward end of the treadle 12, the rear end thereof will be elevated, which action through the connecting rod or pitman 13 will rock the bell-crank lever 14 and throw the sleeve 8 outwardly so as to bring about engagement between the cone-

shaped end 9 thereof and the inner ends of the clutch arms 10. The result is that the two members of the clutch are thrown into operative relation with the pulley ring and the motion of the pulley 7 will be transmitted to the drive shaft 1. When the pressure is relieved from the treadle 12 the spring 18 acting upon the bell crank lever 14 will serve to separate the sleeve 8 from the clutch arms 10, disconnecting the two members of the clutch and throwing the drive shaft 1 out of operation. To start the machine therefore, it is merely necessary to depress the treadle 12 and to stop the machine it is merely necessary to release the pressure upon said treadle. The operation of the machine is therefore wholly within the control of the operator and may be stopped or started at will.

20 *Filler forming table.*—One of the important features of my invention is the mechanism for initially forming the bunch, consisting of the measuring and shaping of the filler tobacco, the application of a bind, thereto, the rolling, compressing and shaping of the bunch with the binder thereon and the delivery of the bunch to the transferring devices. In carrying out this part of my invention, I provide what I term for convenience in description a filler table 19, the same being preferably horizontally disposed and mounted for reciprocation on a platform or surface 20 carried by a bracket 20 secured to or forming part of the main frame as clearly shown in Figs. 2 and 4. Reciprocating movement is imparted to the table 19 from a rock shaft 21 mounted in suitable bearings in the main frame and extending transversely of the machine. The said rock shaft is operated by means of a crank arm 22 thereon which is provided at its inner end with a pin or projection 23 fitting within a cam groove or race 24 in the gear wheel 2. Said rock shaft also has secured thereto and extending upwardly therefrom on opposite sides of the table 19 the arms 25 which are pivotally connected through the links 26 with said table 19. By this construction it will be seen that as the gear wheel 2 is rotated an intermittent reciprocating motion will be imparted to the table 19. Formed in the table 19 adjacent to the forward end thereof is a filler receptacle 27, the same extending entirely through said table and in a direction transversely thereof. The receptacle 27 is of a shape corresponding to that of the bunch to be made and constitutes a shaper and measurer for the filler tobacco. Means are provided for increasing or decreasing the width of the receptacle 27, the same consisting of an adjustable plate 28 having a depending side flange 29 thereon which projects down into and constitutes one of the side walls of said receptacle. The plate 28 has elongated slots 30 therein

through which extend the adjusting screws 31, the said screws constituting a means for locking the plate 28 in any position to which the same may be adjusted. Knives or cutters 32 are provided on the table 19 at the opposite ends of the receptacle 27 and corresponding fixed knives 33 are provided on the bracket 20 at opposite sides of the table 19. The knives 32 and 33 coöperate with each other and serve to sever the projecting ends of the filler tobacco in the receptacle 27 during the reciprocating movements of the table 19. To receive the clipped ends of the filler tobacco, pockets 34 are formed in the table 19 at opposite ends of the receptacle 27.

As will hereinafter appear the table 19 when projected to its extreme innermost position extends beyond the inner end of the bracket 20 and the filler tobacco in the receptacle 27 is forced down through the bottom of said receptacle onto the bunch-making table. To prevent the escape of the filler tobacco while passing between the receptacle 27 in the table 19 and the pocket in the bunch-making mechanism, I provide an automatically movable guard 35. The said guard is secured to or formed integral with two parallel arms 36 which are pivoted at 36 to the forward end of the bracket 20 as shown in Fig. 5. The rear ends of the arms 36 are provided with up-turned fingers 37 which fit within recesses 38 in the lower opposite side edges of the table 19, as most clearly shown in Figs. 5 and 7. The guard 35 is normally maintained in its raised inoperative position by the springs 39 which are attached to the arms 37 and to the bracket 20 or other stationary part of the frame. Said fingers 37 are, however, adapted to be engaged by the shoulders 40 at the rear ends of the recesses 38 to throw the guard 35 down into its operative position; that is to say, when the table 19 is retracted as shown in Figs. 2, 4 and 5, the guard 35 will be in its raised or elevated position with the fingers 37 thereon lying within the recesses 38 and at points removed from the shoulders 40, the said guard being maintained in this position by the springs 39. When the table 19, however, is moved forwardly, said guard 35 will remain in its raised position until the shoulders 40 abut against the free ends of the fingers 37 whereupon the guard will be moved downwardly into its operative position as clearly shown in Fig. 3.

120 *Bunch making mechanism.*—The bunch-making mechanism above alluded to is located beneath the filler table 19 and comprises what I term a bunch-making table 41 having a depression or pocket 42 therein for the filler from the receptacle 27 and the binder to be wound upon said filler. The said table except for the pocket 42 therein has a convex upper surface and is secured

to or formed integral with the sides or arms 42, 44. The arm 44 is located in a plane beyond the adjacent side edge of the table 41, the same being connected to said table by means of a web 43 which is located in a plane beneath the table 41, forming a depression to provide for the movement of said table past other operative parts of the device to be hereinafter described. The 16 sides or arms 42 and 44 are loosely sleeved upon a fixed transverse rod or shaft 46 and upon this rod said arms and the table 41 connected therewith are mounted for oscillation. This oscillatory movement is imparted to the table 41 by means of an extension 47 on the arm 48, which is provided with a pin or stud 48, fitting within a cam groove or raceway 49 in the inner surface of the gear wheel 2. As said gear wheel 2 rotates, therefore, it will impart, through the connections described, an oscillatory movement to the table 41 on the rod or shaft 46 as a center. Extending across the upper surface of the table 41 is a bunch-rolling and 25 compressing belt 50, the same extending around a small roller 51 along one edge of said table 41 and having its adjacent end secured to a rod or bar 52 connecting the upper ends of the levers 53. Said levers are 30 fulcrumed at their lower ends, as shown at 54, to the side arms of the table 41, and at 51, to the side arms of the table 41, and are connected at points intermediate of their ends through the links 55 to the arms or levers 56, 57. The said arms or levers 56, 57 are connected at their upper ends by a 35 transversely extending rod or bar 58 (Fig. 9), and these parts constitute a rocking frame. The said arms or levers 56, 57 are pivoted at 59 to the side arms 42, 44 of the table 41 and the lower end of the arm 56 is formed into an extension 60 or lever 56 is formed into an extension 60 which projects beyond the pivotal point of the lever and is provided with an anti-friction roller 61. The roller 61 is adapted to 40 engage the surface of a cam 62 secured to the fixed shaft 46 or to the edge adjacency part of the main frame. A clamp 63 is provided at the upper end of the rocking frame, made up of the ends 64, 65 and 66, 50 the said clamp comprising a fixed jaw 64 and a pivoted jaw 65 representing hereinafter. The said pivoted jaw 65 is adjusted to be moved into and out of the locking relation to the fixed jaw 64 by means of the 55 thumb nuts 66, as clearly shown. The end of the belt 50 opposite that which is connected to the rod or bar 52 is fastened to be secured by means of the clamp 62 to the ends or levers 56 and 57, and by means of 60 said clamp the tension of the belt 50 may be adjusted to compensate for contraction thereof in due to stretching or the differences in the size of the bunches to be formed, or in the compactness which it is desired to 65 part to said bunches.

Cooperating with the bunch-forming table 41 and the parts above described as being connected therewith are the fixed rollers 67, 68. These rollers are journaled in depending flanges 69 formed by rabbeting or channeling out the under side of the inner end of the platform 20, at 70, as clearly shown in Fig. 4. They are located one above the other, the upper roll 67 being disked out or concaved longitudinally to 75 conform to the shape of the bunch being produced as shown in Fig. 6. The lower roller 68 is smaller in diameter than the roller 67, is cylindrical in form and constitutes merely an idle roller to assist in the formation of the 80 pocket in the belt 50 in which the bunch is rolled and compressed. It should be stated in this connection that the belt 50 extends from the rod 52, to which one end of the same is connected, around the roller 85 51, and thence around the rollers 68 and 67 to its point of connection with the clamp 63. It should also be stated that when the table 41 is in its position of rest as shown in Fig. 5, the belt 50 is loose, but that when 90 the table 41 has been moved to the position shown in Fig. 4, said belt 50 is taut.

Bunch holding mechanism.—Carried by the table 41 at the end thereof opposite the pocket 42, is what I term a bunch holder 71, 95 the same comprising a fixed part 72 secured to the brackets or extensions 73 on said table, and the movable part 74 as shown in detail in Fig. 8. The holder 71 is open at its top, bottom and ends, and the sides thereof which are formed by the inner surface of the parts 72 and 74 are shaped to conform to the bunch to be deposited therein and retained thereby. The inner walls of said holder are inclined to each other, that is, they taper or converge from the upper part of said holder downwardly so as to produce a contracted lower or discharge end. The part 74 of the holder 71 is connected to the part 72 thereof by means of 100 rods 75 on the former which extend through corresponding openings in the latter. The projecting ends of the rods 75 are surrounded by coil springs 76 which engage the heads 77 on said rods and on the rear side of the part 72. By this construction it will be seen that the part 74 is held by spring pressure toward the part 72, but is incapable of outward movement so as to increase the width of the discharge opening 105 of said holder.

The holder 71 is designed to receive the bunch when it has been rolled, shaped, compressed and held in buncher applied thereto, by the table 41, belt 50, roller 67 and the 110 parts 64, 65, fitting therewith, and to deliver the same upon a suitable conveyor and shape to be hereinafter described. The pocket 42 in the table 41, on the other hand, is designed to receive the filler from the 115

receptacle 27, with the belt 50 and binder beneath it. To provide for ejecting the filler from the receptacle 27 into the pocket 42 and for ejecting the bunch from the holder 71 into the conveyer, I employ two vertically reciprocating plungers 78 and 79, secured respectively to the laterally extending arms 80, 81 of a vertically disposed slide member 82, as clearly shown in Figs. 1, 2, 10 and 3. The plunger 78 is located directly above the receptacle 27 in the filler table 19 and the pocket 42 in the bunch-making table 41 when the filler table has been moved to its extreme innermost position and the 15 bunch making table has been moved to its extreme position to the left, at which positions said tables are caused to remain for a short period of time, due to the particular curvatures of the cam grooves by which 20 they are operated. The plunger 79 is located and moves directly above the bunch holder 71 when the table 41 by which it is carried is in the position above described. Both these plungers being connected to a 25 common support, namely, the slide rod 82, are operated simultaneously and in the same direction. When the said plungers are moved downwardly, the plunger 78 serves to force the filler tobacco in the receptacle 30 27 down through the lower end thereof and into the pocket 42 in the table 41, and the plunger 79 serves to force the bunch in the holder 71 down through the lower discharge end of said holder into the conveyer located beneath said holder. The slide rod 82 by which the plungers 78 and 79 are carried has pivoted to it a link 83, which link is in turn pivoted at its lower end to a 35 crank arm 84 on a rock shaft 85 as best 40 shown in Fig. 2. The said rock shaft extends out through the frame of the machine and has upon its outer end a crank arm 86 which carries a stud or pin 87, fitting within a cam groove or race 88 in the 45 outer surface of the wheel 2. By this construction an intermittent up-and-down movement will be imparted to the slide rod 82, and consequently to the plungers 78 and 50 79 carried thereby, through the cam groove 88 and the connections between said groove and said slide rod 82. This said cam groove 88 is so shaped and disposed that throughout the greater portion of the rotation of the wheel 2, it will act to maintain the plungers 78 55 and 79 in their raised position. The high or eccentric portions of said cam groove, however, serve to move said plungers downwardly with a somewhat sudden movement and to retract the same to their normal position in a similar manner. It will thus be seen that while said plungers 78 and 79 are 60 normally held in a raised position they are, once during each rotation of the wheel 2, depressed and almost instantly raised again.

65 *Binder carrier mechanism.*—As has been

stated heretofore, when the filler is ejected from the receptacle 27 and forced into the pocket 42, it moves down upon a binder with which the same is to be covered. It is therefore necessary that means be provided for 70 delivering a binder to a point adjacent to the pocket 42 prior to the insertion of the filler into said pocket. The means provided for this purpose consists of a binder carrier 89, (Figs. 1 and 2) normally located adjacent to one end of the machine within convenient reach of the operator but adapted to be swung around so as to present the projecting end of the binder thereon to the 75 filler as it descends into the pocket 42. The 80 said carrier is made up of a suction box having a flat upper surface and perforations 90 in its top wall. Communicating with said suction box is a laterally extending binder 91 of a vertically disposed rotatably 85 mounted suction pipe 92. To the latter pipe is connected a flexible coupling 93 leading to or communicating with any suitable form of 90 exhausting apparatus. The pipe 92 is mounted in suitable bearings in the framework of the machine and has formed thereon or secured thereto a pinion 94 with which meshes a segmental gear 95 (Fig. 1) on one 95 end of an arm or lever 96, mounted in suitable bearings in the framework of the machine and having a stud or tooth 97 on its opposite end which fits within a cam groove in a disk 98 secured to the main drive shaft 1. The groove in the disk 98 is so disposed that once during each rotation of the drive 100 shaft 1, the same will serve through the connections described to rock the pipe 92 in its bearings so as to swing the binder carrier 89 around to the position shown in Fig. 3 and then reflect the same to its normal position, as shown in Fig. 1. The binder 99 on the carrier 89 projects at one end from the edge of said carrier, as clearly shown in Fig. 3, so that it presents itself above the pocket 42 in the table 41 prior to the introduction of the filler into said pocket. 105

The mechanism above described is that which is employed in the production of a cigar bunch and the operation of the same is as follows. The machine is started by 115 depressing the treadle 12, which throws into operative relation to each other the parts 8 and 16 of the clutch through which the pulley 7 is connected to the drive shaft 1. Assuming the filler table 19 to be in the position shown in Figs. 1 and 4, the filler tobacco is placed within the receptacle 27 in said table, the same being supported from beneath by the bracket 20. The said receptacle serves as a means for measuring the proper quantity of filler tobacco for the size and weight of the cigar to be made and also serves to shape the filler. By this means an unskilled person may prepare, measure and form a filler more readily and quickly than 120 125 130

an operator with years of experience. As the wheel 2 is now in operation, it will serve, after the filler has been placed in the receptacle 27, to move the table 19 forwardly until it reaches the position shown in Fig. 3, when the motion of said table is automatically arrested. During this movement of the table 19 the cutters 32 and 33 are brought into cooperative relation to each other and serve to sever the projecting ends of the filler tobacco, in the receptacle 27, which projecting ends fall down into the pockets 34 on opposite sides of the table 19. That portion of the filler which is removed is therefore within convenient reach of the operator to be utilized in the formation of one of the succeeding fillers in the receptacle 27. During said operation of the table 19, the guard 35 will, through the action of the shoulders 40 on the fingers 37, be thrown downwardly into its operative position, as shown in Fig. 3. In the meantime, the bunch-making table 41 will have been moved to its extreme position to the left with the pocket 42 therein located directly beneath the receptacle 27, and with the bunch holder 71 located directly above one of the receptacles on the bunch conveyor. The binder carrier 89 will also have been moved from the position shown in Fig. 1 to the position shown in Fig. 3 with the projecting end of the binder 99 thereon located over the pocket 42 and within the path of movement of the filler from the receptacle 27 to said pocket. The belt 50 on the table 41 will also have been slackened. The cam groove 88 in the wheel 2 now acts to move downwardly the rod or shaft 82 and the plungers 78 and 79 connected therewith. During this movement of said plungers, the former serves to eject the filler from the receptacle 27 and to force the same down into the pocket 42 above the binder 99 and the belt 50. At the same time the plunger 79 acts to eject the finished bunch from the holder 71 into the receptacle provided therefor in the conveyor located beneath said holder. As the filler is forced down into the pocket 42 on top of the projecting end of the binder 99 and on top of the belt 50, it produces a fold or pocket in the belt 50 itself, which partially surrounds the bunch in said pocket 42. As the filler is forced from the receptacle 27 into the pocket 42 any portions or particles of tobacco are prevented from escaping by the guard 35 which, as shown in Fig. 3, forms a closed passage between these two parts. After having been depressed the plungers 78 and 79 almost immediately return to their normal raised positions out of the paths of movement of the filler table 19 and the bunch-making table 41. When said plungers are raised, the table 19 returns to its normal position, as shown in Fig. 1, for the repetition of the operation above de-

scribed. As it recedes it releases the shoulders 40 thereon from the fingers 37 and enables the springs 39 to return the guard 35 to its raised position. The oscillating table 41 now begins its movement to the right through the action of the cam groove 49 on the pin or stud 48 carried by the extension 47 of the side arm 43 of said table. In so doing the filler in the pocket 42 is moved to a position beneath and slightly beyond the rollers 67 and 68, the same being lifted from said pocket by the belt 50 and raised to such degree as to enable the convex portion of said table to pass beneath the bunch. The complete bunch filler with the binder applied thereto now occupies a position within the fold in the belt 50, substantially as shown in Fig. 4. The continued movement of the table 41 to the right causes the movement of the belt 50 around the rollers 68 and 67 with the result that the binder is tightly wound upon the filler and the bunch is rolled in contact with the belt. At the same time, however, the tension of the belt 50 is increased and continues to increase from a short time after the movement of said table 41 is started until it reaches the limit of its movement to the right. This tightening of the belt 50 is automatically effected by the movement of the roller 81 (Fig. 2) on the arm 56 in contact with the irregular surface of the fixed cam 62. The bunch is therefore subjected to a gradually increasing compression within the fold or pocket in the belt 50 in which it is held and to a rolling action due to the movement of the belt over the rollers 67 and 68. The concavity of the roller 67, with which the belt cooperates, and the proximity of the bunch to the said roller within a fold or pocket of the belt insures shaping of the belt in such manner as to impart the desired compression to the bunch to properly shape the latter. The degree of compression imparted by the belt 50 to the bunch being made may be regulated by adjusting the free end of said belt in the clamp 63. As the table 41 reaches its extreme position to the right it passes from beneath the bunch being made and rolled, and the bunch is allowed to fall, or is ejected by the tension of the belt 50, into the bunch holder 71. The table 41 now begins its movement to the left carrying with it the bunch in the holder 71 to be delivered by the plunger 79 onto the conveyor the next time said plunger 79 is depressed. During the latter movement of said table 41, it will be obvious that the belt 50 will be gradually slackened so that when it again reaches the position shown in Fig. 3, it will be in condition to receive another filler in the pocket 42.

Bunch conveying and shaping mechanism.—It has been stated that the completed bunches from the bunch-making mechanism are ejected successively from the bunch

holder 71 on the table 41 by the plunger 79 and delivered upon a bunch conveyer and shaper. This mechanism which for the purpose of convenience of expression will here-
 5 after be designated a conveyer extends longitudinally of the machine and is made up of an endless series of bunch receiving cups or receptacles 100, which are arranged at regular intervals apart and extend trans-
 10 versely of the machine. Each of said cups is formed on its opposite sides with lugs or ears 101, to which are pivoted the links 102, which go to make up the complete conveyer as clearly shown in Fig. 3. A flexible chain
 15 conveyer is thereby produced and the same is mounted upon and passes around the sprocket wheels 103, 104, the former being provided with a ratchet wheel 105 through which an intermittent movement is impart-
 20 ed to said conveyer. The said sprocket wheels 103 and 104 are mounted respectively upon the transverse shafts 106, 107. Coöperating with the ratchet wheel 105 is a pawl 108 which is pivoted to an arm 109 loosely
 25 mounted upon a stud or shaft 110 and adapted to be engaged by a cam 111 on the main drive shaft with which it is held in contact by a spring 111^a. The said pawl and the arm to which it is connected are normally
 30 maintained in operative relation to the ratchet wheel 105 by gravity as shown, or by means of a spring or other analogous device. By this construction, it will be seen
 35 that as the shaft 1 rotates, the cam 111 will be brought into engagement with the arm 109 and move the latter outwardly away from said shaft, causing the tooth of the pawl 108 which is in engagement with the ratchet wheel 105 to rotate said ratchet
 40 wheel and the sprocket wheel 103 connected therewith. When said sprocket wheel is rotated, motion will be imparted to the bunch conveyer which passes around the same. As soon as the eccentric face of the cam 111
 45 passes beyond the arm 109, the said arm and the pawl 108 will be returned by the spring referred to to their normal positions. It will thus be seen that once during each complete rotation of the shaft 1, movement will
 50 be imparted to the bunch conveyer. The extent of this movement is exactly equal to the distance between two of the cups 100, of which said conveyer is made up. The conveyer is moved the distance of one step
 55 thereof and then remains at rest until the cam 111 again engages and moves outwardly the arm, 109. To prevent reverse or backward movement of the conveyer, I provide a dog 112 which is held in yielding contact
 60 with the teeth of the ratchet wheel 105 by a spring 113 and enables said ratchet wheel to rotate freely in the direction in which it is turned by the pawl 108, but prevents the rotation of said ratchet wheel and of the

parts connected therewith in the opposite 65 direction.

The bunch conveyer is so disposed upon the sprocket wheels 103 and 104 that during the periods of rest between its intermittent step-by-step movements, one of the cups 100 will be located directly beneath the bunch holder 71 when the table 41 has been oscillated and is held in its extreme position to the left, so that when the plunger 79 is drawn downwardly, one of said cups will be in proper position to receive the bunch ejected from said holder 71. The cavity or hollowed-out portion in each of the cups 100 corresponds in shape with that of the bunch which is introduced thereinto and each of said cups is provided with a cover 114 (Fig. 3) which projects down into said cup, and is concaved on its lower surface so that the space defined by the concavity of each cup and that of the cover or lid thereon will 75 exactly correspond with the shape of the bunch introduced into the cup. Suitable means to be described later serve to lock the covers 114 in their closed positions and retain the bunches in the cups 100 during the greater part of the revolution of the bunch conveyer around the sprocket wheels on which it is mounted.

Inclosing the sprocket wheels 103, 104 and extending longitudinally of the machine between said sprocket wheels is a heating and drying case or drum 115 (Figs. 3, 11 and 16) the same being made up of the horizontally disposed top and bottom walls 116 and the parallel vertically disposed side walls 117, connected with the top and bottom walls 116 and extending from the sprocket wheel 103 to the adjacent sprocket wheel 104. In this heating case or drum 115 is located a coil of pipe 118 through which steam, air, gas or other heating medium may be passed by way of the pipes 119 and 120. As the bunch conveyer passes around, above and below the walls 116 of the case 115 and as said case is closed along 95 its sides so as to prevent the escape of heat, the bunches contained in the cups or receptacles 100 of the bunch conveyer will be heated and dried, and consequently set, during the passage of a conveyer around the 100 sprocket wheels on which it is mounted. The cups 100 and the lids or covers 114 therefor hold the bunches in compressed condition after they are delivered from the bunch holder 71 and while in this compressed condition the same are subjected to the heating and drying action of the heating medium in the case 115 with the result that when said bunches have been carried 105 around the sprocket wheels 103 and 104, they will be compressed, dried and set into proper size and shape.

As the cups 100 successively approach the

bench holder 71, the bunches contained therein are removed and carried to the wrapper-applying mechanism. To do this, however, it is necessary that the cover or lid of the particular cup from which the bunch is being removed shall be opened. It is also necessary, as will be obvious, that the lid or cover of the cup which is receiving a bunch from the bunch holder 71 shall be opened. Two cups 100 of the bunch conveyor, must therefore be opened at the same time while all of the remaining cups at said conveyor are kept closed. Means must be provided therefore for lifting the lids of the different cups and opening the lid of the cup 100, receiving the bunch contained therein, to be opened, and for closing the lid of that cup which has just received a bunch from the bunch holder 71. To accomplish this, there is provided upon each of the cups 100 a longitudinal projecting arm 104, to which is pivoted an lid or cover 114. Each of said covers is provided with an arm 122 extending beyond the pivotal point of said cover and with a pivoted spring catch 123 at its opposite or free end which forms part of a lock for retaining the cover in place, co-operating with the portion 109 vertically recessing slides 124, 125 maintained in suitable grooves 126 on the side of the cup 100 and provided with grooves 127 for the reception of the arms 104 of the lid or covers 114. The groove 127 in the slide 125 is formed by a slightly extending lug or projections 128, 129, the former lug being located at the upper right-hand corner of said slide and the latter being located beneath the lug 128, adjacent to the opposite side edge of said slide. The groove 127 in the slide 124 is formed by two inwardly extending lugs or projections 130, 131, the former being located at the upper left-hand corner of said slide and the latter being located beneath the former and adjacent to the right-hand edge of the said slide. The inner ends of the lugs 128 and 129 and the inner ends of the lugs 130 and 131 terminate in vertical stops which are removed from each other so that each of the said grooves is made in two parts which are separated from each other at the center of the slide; the purpose of this construction will presently appear.

Now, it will be noted by reference to Fig. 1 that the slide 125 is located in a direct line with the bunch holder 71 when the latter is in its depressed position, as shown in Fig. 8, of the drawings, and in a direct line with the cup 100 on the conveyor which is receiving a bunch from said bunch holder. It will also be noted that the slide 124 is located directly opposite the cup 100 of the bunch conveyor which lies adjacent to the cup last referred to, and is about to pass beneath the bunch holder to be filled. The latter cup is the one which is having or has had its bunch removed therefrom, and the two cups last referred to are the ones which must necessarily have their lids or covers 114 open. For convenience in the further description of the operation of the device, I shall refer to the two cups in question as cup A and cup B, the former being the one receiving a bunch and the latter being the one from which a bunch has been removed.

The slide 124 has pivoted to it through the link 123 the lever 133 (Fig. 15), fulcrumed to a fixed part of the machine and having a pin stud or projection 134 thereon which fits within a cam groove 135 in the wheel 3. The slide 125 has pivoted to it through the link 126 a lever 137 fulcrumed to a fixed part of the machine and having a pin stud or projection 138 thereon which fits within the cam groove 139 in the wheel 3. By this construction, it will be observed that during the rotation of the wheel 3 which is connected to the main drive shaft 1, the reciprocating movement will be imparted to each of the slides 124 and 125.

From the foregoing description, it will be obvious that when the arm 122 of one of the lid or covers 114 lies within the groove 127 of one of the slides 124, 125, the downward movement of said slide will serve to raise and open said lid or cover, whereas an upward movement of said slide will serve to lower and close said cover. The arms 122 of the lids 114 of two of the cups 100 will always be located within the grooves 127 of the two slides 124, 125. Assume the cover to be at one of its periods of rest, as shown in Fig. 3, with the cup B empty, by reason of the fact that the bunch contained therein has been removed, and with the cup A in the act of being filled by the operation of the plunger 79. It will be obvious that the arm 122 of the lid or cover 114 of each of the cups A and B will be located in the grooves 127 of the slides 125 and 124, respectively. The bunch conveyor moves, of course, in the direction of the arrow shown in Fig. 3 and when it begins to move the slide 125 begins to rise with the result that the lid 114 of the cup A is moved downwardly and closed, as shown in Fig. 10. At the same time the arm 122 of the cup B moves from the slide 121 toward the slide 125. The same passes from above the lug 129 of the slide 124, but is still maintained in its open position by the engagement of the lug 128 therewith. When a portion of the extent of movement of the bunch conveyor has been traversed, therefore, the arm 122 of the cup B will be located directly beneath the lugs 128 and 129 of the slides 121 and 125 respectively, and the arm 122 of the cup A will have passed beyond the lug 130. The slide 125 is now moved down-

wardly without again raising the lid of the cup A, as the lug 130 passes freely by the arm 122 of the lid of said cup A. When said slide 125 reaches its lowermost position, it engages the arm 122 of the lid of the cup B and serves to retain said lid in its raised position until the arm 122 thereof passes between the lugs 130 and 131 on opposite sides of the groove 127 of the slide 125. As soon, however, as the slide 125 has been moved downwardly, and the lug 130 thereof engages the arm 122 of the lid of cup B, the slide 124 begins its upward movement. This movement of the latter slide 124 may be effected without any action on the arm 122 of the lid of cup B, as said arm has passed beyond the path of movement of the lug 129. When said slide 124 is in its raised position, it receives beneath the lug 128 thereof the arm 122 of the lid 114 of the next succeeding cup, which I have designated for clearness of description, by the reference letter C. As soon as this engagement takes place the slide 124 moves to its lowermost position carrying with it the arm 122 of the lid of cup C, thereby raising and opening said lid, as clearly shown in Fig. 11. Both slides 124 and 125 are now in their lowermost positions and the lids of both cups B and C are opened. In the meantime, however, the cup A with the lid thereof closed down thereon has passed beyond the vertical plane of the plunger 79 and the cup B has taken its place ready to receive a bunch from the bunch holder 71. The operation above described is effected automatically during each of the intermittent movements of the bunch conveyor.

The catch 123 on each of the lids or covers 114 is pivoted to the free end of said cover and is provided with a spring tail-piece 149, adjacent to its pivotal point which tends to throw the same outwardly into locking position when brought into engagement with its keeper. Said catch extends downwardly from said lid or cover when the latter is in its closed position and is provided with an inclined face 141 and a shoulder 142, adapted to be projected through the opening 113 in the bottom wall of the cup 100, as clearly shown in Figs. 13 and 14. When the lid 114 is moved to its closed position, as shown in the two figures referred to, the spring 140 acts to swing the catch 123 on its pivot to bring the shoulder 142 thereon into locking engagement with one wall of the opening 113 which constitutes the keeper. As the bunch within the cup 100 is of slightly greater diameter than the cavity in said cup 100 formed by the body thereof and by the lid or cover 114, it is necessary that means be provided for positively forcing said lid or cover to its closed position and locking it in such position until it is ready to be opened. It is also important that means be provided

for automatically releasing the lock by means of which said lid or cover is secured to the body of the cup. The means provided by me for this purpose consists of a shaft 144 mounted in fixed bearings in the frame 70 of the machine and intermittently rotated by a milled gear 145 (Figs. 1 and 2) secured to one end thereof and meshing with the gear wheel 2. The inner end of the shaft 144 is provided with a beveled pinion 146 which meshes with a pinion 147 on a shaft 148 extending at right angles thereto. The said shaft 148 or the hub of the pinion 147 is provided with a laterally extending lug or depressing arm 149 which is moved through the gearing described in the direction of the arrow shown in Fig. 14. The said lug or arm is so disposed that when the lid 114 of the cup A which has just been filled with a bunch from the bunch holder 71 has been moved downwardly to its closing position by the means above described, it will engage the upper free end of said lid, as shown in Fig. 14 and force the same downwardly to its completely closed position. In so doing the beveled edge 141 of the catch 123 rides over the edge of the opening 113, against the action of the spring 140 until the head of said catch passes entirely through said opening, when the spring 140 operates to swing the catch 123 outwardly so that the shoulder 142 thereon moves into locking engagement with its keeper. The lid 114 is thereby locked in its closed position and the lug 149 passes beyond the same. The shaft 148 carries a pinion 150 (Fig. 1) which meshes with a pinion 151 on a counter shaft 152 (Figs. 10 and 12). The said counter shaft or the pinion 151 thereon has secured to it a laterally extending lock-releasing lug or arm 153, which through the gearing described is rotated in a direction opposite that of the lug 149. The said lug 153 is so disposed that just prior to the depression of the slide 124 for the purpose of opening the lid 114 of the cup B, it will act upon the catch 123 of the lid of said cup B, as shown in Fig. 13, to force the same inwardly against the action of the spring 140, this position of the parts being shown in Fig. 13. Before the lug 153 moves out of engagement with the catch 123, the slide 124 is moved downwardly with the effect of elevating the lid of the cup to the position shown in Fig. 11.

To provide for the intermittent movement of the shaft 144 and consequently of the lid-closing and lock-releasing mechanism above described, once during each rotation of the drive shaft 1, the gear 145 is, as heretofore stated, milled. While the teeth thereof are in mesh with the teeth of the wheel 2, the gear 145 and consequently the shaft 144 will be rotated. As soon, however, as the teeth of the wheel 2 pass into the smooth or

mutilated portion of the gear 145, the latter and consequently the shaft 144 will cease to rotate. In order to throw the teeth of the mutilated gear 145 into mesh with the teeth of the wheel 2 once during each rotation of the latter, I provide at one point on the wheel 2 a radially projecting tooth 134 (Fig. 2) which is adapted to engage a corresponding projection 135 on the gear 145.

From the foregoing, it will be observed that I deliver the bunches as they are formed from the bunch holder 71 successively into the cups or receptacles 100 and that said bunches are carried by said conveyer around the heating and drying case 115 and successively removed one by one from said cups after they have made one complete revolution. During this movement of the conveyer the bunches are held under compression in the several cups or receptacles thereof and are subjected to the heating and drying action of the heating coil 118 with the result that when they are removed from the conveyer they are dried and set to the proper size and shape. This is an important feature of the invention.

Bunch transferring mechanism.—The means provided for removing the bunches from the cups 100 of the bunch conveyer 156, (Figs. 1, 2, 3, 17, 18 and 21) which is adapted to lift the bunches successively from said cups or receptacles and move the same over to and deliver them into the cluster of rolls constituting a portion of the wrapper applying mechanism. The transferrer 156 is mounted upon and actuated by a rock shaft 157, having suitable bearings in the main frame of the machine, extending transversely thereof and located above the shaft 4, heretofore referred to. The said transquirer consists of an arm 158 sleeved upon and secured to the shaft 157 and having attached to its outer or free end the knives or cutting blades 159, 160. The rigid connection between the blades 159, 160 and the arm 158 may be effected in any suitable manner, but I have shown a rod 161 secured to the arm 158 and extending outwardly therefrom from opposite sides thereof, the said rod being polygonal in cross section and extending through correspondingly shaped openings in said blades, and by this arrangement turning movement of said blades 159, 160 on the arm 158 is effectually prevented. The outer ends of the blades 159, 160 are provided with the cutting edges 162, 163, which are in alignment with each other and are separated by a distance equal to the length of one of the cups or receptacles 100, heretofore referred to. The blade 159 has been shown as extending substantially parallel to the arm 158 whereas the blade 160 has been shown as being bent laterally at a point adjacent to the rod 161 and then bent forwardly. Cooperating with these parts and constituting portions of the bunch transquirer are the needle carrying arms 164, 165, the same being provided respectively with sleeves 70 166, 167, which fit loosely upon the shaft 157 so that they are capable of movement on said shaft in the direction of the length of the latter. That is to say, by means to be presently described, said arms 164 and 165 are adapted to be moved laterally of the machine, and toward and away from each other. The said arms 164, 165 are provided with rectangular openings through which the rod 161 passes and said rod is provided 75 on its opposite ends with knobs or washers 168 for limiting the outward movement of said arms. The free ends of said arms terminate at points outside of but opposite to the free ends of the blades 159, 160 85 which carry the cutters 162, 163, to effect which result the arm 164 has been shown as extending substantially parallel to the arm 158 and the blade 159, whereas the arm 165 has been shown as being bent laterally 90 at a point adjacent to the rod 161 and then forwardly so as to be substantially parallel to the arm 158 and the blade 160. The free end of the arm 164 carries an inwardly extending needle 169 which is adapted to project through the opening 170 in the blade 159, and the free end of the arm 165 is provided with a series of needles 171 adapted to project through corresponding openings 172 in the adjacent blade 160. But one 100 needle 169 has been shown, whereas three needles 171 have been illustrated; it is obvious, however, that the particular number of needles employed is not essential and I may in practice increase or decrease the 105 number illustrated in the drawings. The needles referred to are adjustably secured to the arms in which they are carried for the purpose of regulating the extent of penetration of the same into the opposite 110 ends of the bunch and to prevent the complete removal of the same from the openings 170 and 172 through which they pass. The object of preventing the complete retraction of these needles from the openings 115 in the cutting blades is to avoid the possibility of said needles not properly registering with the openings in said blades when they are moved to their inward position. One means for adjusting said needles has 120 been illustrated in Fig. 18 in connection with the arm 164 and the needle 169. The same means, however, may be provided for the adjustment of the needles 171 in the arm 165. A tapering internally screw-threaded opening 173 is provided in the arm 164 into which is adapted to screw a split clamping nut or sleeve 174, through the center of which the needle 169 passes. By 125 properly locating the needle 169 in the 130

clamping nut 174 and screwing the latter into the opening 173, it is obvious that said needle 169 may be secured in proper position to the arm 164.

- 5 To provide for the automatic lateral movement of the arm 165, and the needles 171 carried thereby, I employ a rod 175 (Figs. 17 and 19) mounted in the main frame of the machine and capable of movement in the direction of its length transversely of said machine. The outer end of the arm 175 is provided with a downwardly extending tooth or projection 176 which fits within a cam groove or race 177 in the periphery of the gear wheel 6. The opposite or inner end of said rod 175 carries a depending forked plate or arm 178 whose branches straddle and fit within an annular groove 179 in the sleeve 167 of the arm 165.
- 10 A rod 180 similar to the rod 175 is provided for the operation of the arm 164. The said rod 180 is mounted in the main frame or in an extension thereof so that it is capable of movement in the direction of its length parallel to the shaft 157 and transversely of the machine. The outer end of said rod carries a depending tooth or projection 181 which fits within a cam groove or race 182 in the wheel 6 (Fig. 1), heretofore referred to. The inner end of the rod 180 has secured to it a forked arm or plate 183 similar to the plate 178, the branches of which straddle and fit within an annular groove 184 in the sleeve 166 of the arm 164 (Figs. 17 and 19).

Secured to the rock shaft 157 is a pinion 185, with which meshes a segmental rack 186 on the end of a bell crank lever 187 fulcrumed upon a fixed part and carrying upon its other arm a tooth or projection 188 which fits within a cam groove or race 189 in the wheel 6 as shown in Fig. 3. Through the pinion 185, the segmental rack 186 and the operating means for the latter, an intermittent oscillating or rocking movement is imparted to the shaft 157 and to the bunch transfer 156 mounted thereon. The cam groove 189 is so shaped and disposed that it will maintain the bunch transfer 156 normally in its raised position at a point between the bunch conveyor and the wrapper applying mechanism, as indicated in dotted lines in Fig. 3. When the bunch conveyor begins one of its intermittent progressive movements and the lid 114 of the cup or receptacle 100 from which the bunch is to be removed has been opened, as heretofore described, the bell crank lever 187 is rocked through the action of the cam groove 189 on the pin or projection 188 so as to throw the segmental rack 186 to the left. In so doing the shaft 157 is rocked, by the means described, so as to throw the bunch transfer 156 down into a operative relation with the cup or receptacle 100, whose

lid has been opened. During this movement of said transfer the arms 164 and 165 are in their outermost positions, that is to say, the needles 169 and 171 carried by said arms do not project through the blades 159 and 160. In other words said needles are in the position in which the needle 169 is shown in Fig. 18 of the drawings. As the blades 159 and 160 move in close contact with the outer open ends of the cap or receptacle 100, the cutting edges 162 and 163 thereon serve to clip off any projecting portions of the bunch in said cap or receptacle. By this action the bunch is more fully prepared for the subsequent application of the wrapper thereto, which insures a more finished product when the wrapper has been applied, and also prevents the breaking or destruction of the wrapper which would otherwise be apt to occur if the projecting ends of the bunch were not removed. When the bunch transfer has reached its extreme lowermost position, as shown in Fig. 17 of the drawings, the arms 164 and 165 are moved inwardly toward each other by the action of the cam grooves 177 and 182 on the rods 175 and 180 which are connected to the sleeves 167 and 166 in the manner above described. As soon as this action takes place, the needles 169 and 171 are caused to penetrate the head and tuck ends of the bunch in the receptacle 100 and thereby fasten themselves to said bunch. The bell crank lever 187 is now rocked in the opposite direction by the engagement of another eccentric portion of the cam groove 189 with the pin or projection 188, with the result that the shaft 157 is also rocked in the opposite direction and the bunch transfer 156 is moved to the left until it reaches the position shown in Fig. 3 of the drawings, with the bunch removed from the receptacle 100 and engaged by the needles 169, 171, located directly over the cluster of wrapper applying rolls. The arms 164 and 165 are now moved outwardly to their normal positions through the action of the cam grooves 177 and 182 on the rods 175 and 180, with the result that the needles 169 and 171 are disengaged from the bunch and the latter is allowed to drop by gravity into the cluster of wrapper applying rolls. When this takes place the bell crank lever 187 is again rocked to the left so as to return the bunch transfer 156 to its normal upright position between the bunch conveyor and the wrapper-applying mechanism, ready for the repetition of the operations above described. It will be noted that all of these operations are automatic throughout, and it will also be noted that the bunch transfer 156 serves the functions of severing the projecting ends of the bunches in the caps or receptacles 100 and of successively removing the bunches from 100

said receptacles and depositing them in proper position with respect to the wrapper-applying mechanism. It will also be observed that as the needles 169 and 171 are caused to penetrate the opposite ends of each bunch, they produce a vent at both the head and tuck ends of the bunch and thereby insure a free draft through the bunch. They also provide in this manner that the completed cigar shall be what is known as a "free smoker" which is highly essential.

Wrapper-applying mechanism.—The parts which have been heretofore described are these which go to make up the bunch making mechanism and the means for delivering the bunches successively to the wrapper-applying mechanism. The latter mechanism consists generally of a cluster of rotary wrapper-applying rolls designated as a whole by the reference numeral 190 (Figs. 1, 2, 3, 24, 25, 26 and 12), the wrapper carrier 191 for properly presenting a wrapper to the bunch within said rolls, the tucking needle 192 for forcing and holding one end of the wrapper down into contact with the bunch within said rolls, the wrapper-cutting die 193, and the traveling and revolving roller 194 (Figs. 1 and 50) which cooperates with said die for cutting the wrappers in proper shape and for lifting the wrappers therefrom and delivering the same successively to the wrapper carrier 191, said roller constituting a wrapper transfer for delivering the wrapper from the die to the wrapper-feeding and wrapper-applying mechanism. The die 193 is mounted upon the bed 195 located at one side of the machine opposite the rolls 190 and said bed is provided with an opening 196 through which projects a boss 197 extending downwardly from a plate 198 located on the upper side of said bed. The opening 196 is of greater dimensions than the boss 197 which projects therethrough, so that said boss is capable of movement in all directions in said opening. The bed 195 is also provided on opposite sides of the opening 196 with elongated slots 199, 200 through which extend the bolts 201 in the plate 198. The lower ends of said bolts are provided with nuts 202 by means of which the plate 198 may be locked to the bed 195. By loosening the bolts 201, however, the plate 198 may be moved longitudinally of the bed 195,—that is to say, in the direction of the length of the rolls 190,—the bolts 201 moving in the elongated slots 199 and 200, and the boss 197 moving in the opening 196. Said plate 198 is therefore capable of longitudinal adjustment on the bed 195. Located above the plate 198 is a substantially circular plate or disk 203, the same being capable of turning movement on the plate 198. The said disk 203 is provided with a central opening 204,

which registers with the opening through the boss 197 and said disk is also provided with a thickened portion on its under side around said opening 204, which has formed in it an annular groove, channel or recess 205. This groove 205 receives an annular rib or projection 206 on the upper face of the plate 198. Said groove 205 and the rib 206 which fits theron serve as a guide for the disk 203 in its turning movement on the plate 198. Extending upwardly through the plate 198 is an adjusting bolt 207, which projects through a segmental slot 208, formed in the disk 203 concentric with the opening 204 in said disk. The upper end 209 of the bolt 207 is provided with a nut by means of which said disk 203 may be locked to the plate 198. By loosening said nut, however, the disk 203 is capable of turning movement on the plate 198. It will thus be seen that the disk 203 is capable of axial adjustment on the plate 198. The die 193 which has the cutting edge at its upper end shaped to conform to the contour of the wrapper to be cut, is secured to the disk 203 by means of the brackets 202. The said die extends up through and to a point above the table 210 which table is located above and parallel to the disk 203 and secured to said disk by means of the screws 211. Said die 193 passes through the tubular spacing blocks 212, which serve to separate and hold in proper relative positions the disk 203 and the table 210. The die 193 is hollow, as shown, and communicates with the opening 204 at the center of the disk 203. Within said die and lying in close relation to the inner surface thereof is an upwardly spring-pressed die-clip 213, the same being provided with perforations 214 and normally lying in substantially the same plane with the cutting edge of said die. The said bed 213 is secured to the bolts 215 which extend down through the disk or plate 203 and are provided on their lower ends with nuts 216, adapted to engage the under side of said disk 203 for the purpose of limiting the upward movement of the bed 213 as shown in detail in Fig. 51. The bolts 215 are surrounded by coil springs 217 which serve to maintain the bed 213 normally at the limit of its upward movement, but provide for the yielding of said bed at the proper time. It has heretofore been stated that the plate 198 is capable of longitudinal adjustment on the bed 195 of the machine, and that the disk 203 is capable of axial adjustment on the plate 198. Said plate 198 is also capable of lateral adjustment on the bed 195, that is, an adjustment transversely of the rolls 190. The latter adjustment is effected by the provision of transverse slots 218 in the plate 198 in which the bolts 201 are located.

It will be obvious that when the nuts 202

on the lower ends of the bolts 201 are loosened, the plate 198 and the parts carried thereby may be moved transversely of the rolls 190 along the slots 218. The plate 198 is also provided at the corners thereof or at three or more different points with adjusting screws 219 provided for the purpose of regulating the position of the plane of the upper face thereof. These adjusting screws 218 extend through the plate 198 and are adapted to operate against the upper surface of the bed 195. If it be desired to raise the outer end of the plate 198 or depress the inner end thereof, this result may be effected by loosening the nuts 202 on the lower ends of the bolts 201, screwing in the two set screws 219 at the outer end of the plate 198, and screwing out the two set screws 219 at the inner end of said plate. By now tightening the nuts 202 on the ends of the bolts 201, the plate 198 will be held in its adjusted position. It is, of course, obvious that by reversing the operation just described the plate 198 may be tilted in the opposite direction and it is also obvious that by means of the set screws or adjusting screws 219, the plate 198 may be tilted in any other direction. Now as the plate 198 is capable of longitudinal and lateral adjustment on the bed 195 and is capable of tilting adjustment on said bed, and as the disk 203 is capable of axial adjustment on the plate 198, it will be apparent that as the die 193 is secured to the disk 203, said die may be adjusted bodily, both longitudinally and transversely of the bed of the machine may be axially adjusted, and may be adjusted so as to vary the position or inclination of the plane of the upper cutting edge thereof. These various adjustments of the die 193 are provided for a purpose which will presently appear. The bed 195 is provided on one side of the die 193 and table 210 with a shelf or extension 220 for receiving and supporting the tobacco leaves which are to be subsequently cut up into wrappers. It also has one end or side thereof adjacent to the die 193 and table 210 cut away, as shown at 221, and provided with a flange 222 for the attachment of a bag 223 to catch the scraps or off-falls from the die 193 and table 210. The said bag 223 is slotted so that it may be removably connected with the buttons or projections 224 on the bed 195.

The wrapper-transferrer or roller 194 cooperates with the die 193, the same being mounted on a vertical axis to revolve over the upper surface of said die and over the upper surface of the wrapper carrier 191. The said roller is hollow, preferably cone-shaped, and is mounted for axial rotation in addition to its revolving movement. The same is provided with closed heads 225, 226 and with a series of perforations 227 con-

forming in arrangement and outer contour with the cutting edge of the die 193. The revolving and rotary movement of the roller 194 are derived from the shaft 4 which is extended outwardly beyond the wheel 5, as 70 shown in dotted lines in Fig. 1. The said shaft 4 has secured to its outer end a gear wheel 228 which meshes with a gear wheel or pinion 230, the latter in turn being provided with a bevel pinion 230 meshing with 75 a corresponding bevel pinion 231 on a hollow vertically disposed shaft or tube 232. The latter shaft is located and has a bearing within a fixed sleeve 233, extending through an opening in the bed 195 and provided with a flange 234, by means of which it is secured, bolted or otherwise secured to said bed. The hollow shaft 232 extends up above the bed 195 and has secured to it by means of a key 235 or other suitable device the 80 tubular portion or hub 236 of the bracket arm 237, the upper end of the hollow shaft 232 above the hub 236 being closed by a cap 238.

The outer or free end of the bracket arm 85 237 is provided with bearings for the hollow stem 239 of the roller 194 and constitutes a support for said roller. Secured to the flange 234 of the fixed sleeve 233 is a mutilated gear 240, which meshes with a 90 pinion 241 on the stem 239 of the roller 194. The hub of the mutilated gear 240 constitutes a support for the hub 236 of the bracket arm 237, and between these two parts ball bearings 243 are provided. The 100 hollow stem 239 of the roller 194 has bearings in said and is supported by the lower end of the hub 236 just within the pinion 241.

From the foregoing description, it will be seen that as the shaft 4 is rotated, it will, 105 through the gearing described, impart a turning movement to the tubular shaft 232. As the latter shaft turns, it carries with it the bracket arm 237 and the roller 194, whose stem is mounted therein, causing said 110 roller to revolve about the hollow shaft 232. At the same time the pinion 241 moves in mesh with the teeth of the mutilated gear 240 and an intermittent, rotary movement of the roller 194 is effected. During the revolution of the roller 194, the same moves over and in contact with the upper cutting edge of the die 193, and serves to cut the tobacco leaf placed upon said die into proper shape for the wrapper. By means which will presently be described, the wrapper, as it is cut on the die 193, is lifted therefrom by the roller 194. The perforations 227 in the roller 194 preferably extend completely around it so that the opposite ends of the 125 series of openings 227 will both lie in a single plane passing through the longitudinal axis of said roller. The gear 240 is mutilated in order to provide for the rotation of the roller 194 while it is passing over the 130

die 193 and to stop said rotation when said roller passes beyond said die. In order to prevent any rotary movement of the roller 194 after the same has passed from the end of the die 193 and after the pinion 241 passes from the teeth of the gear 240 to the mutilated portion thereof, I provide upon the stem 239 of the roller 194 a collar 244 having a flat face at one point in its periphery, the said collar moving in contact with a presser block 245 on the end of a spring 246 carried by the bracket arm 237. The flat face of the collar 244 is so disposed that when the roller 194 passes from the end of the die 193, the same will be opposite the presser block 245. The rotation of said roller, due to momentum, is therefore instantly arrested as soon as the necessity for its rotation ceases.

The fixed sleeve 233, heretofore referred to, is provided with a lateral extension or nipple 247 at one point for the application of a suitable suction pipe. The said sleeve 233 is also provided with a lateral extension or nipple 248 which is connected through a flexible pipe or coupling piece 249 with a valve casing 250 secured to the under side of the boss 197 on the plate 198 and communicating with the opening in said boss. Opposite the nipple 247 on the sleeve 233, the hollow shaft 232 is provided with a series of perforations 251 and opposite the nipple 248 on the sleeve 233, said shaft 232 is provided with a series of perforations 252. Through the perforations 251, the suction from the main suction pipe may act upon the interior of the hollow shaft 232 and through the perforations 252 in the shaft 232, the suction from the same source may act upon the valve casing 250, and through the latter upon the interior of the die 193. In the valve casing 250 is mounted the flap valve 253, the same being mounted upon a rock shaft 254 projecting beyond the casing 250, and adapted to engage a seat 255 when in its closed position. The said valve is normally held in its closed position and after operation is returned to its closed position by means of a spring 256 secured at one end to a stationary part of the casing 250 and engaging at its opposite end a crank 257 on the shaft 254. The said crank is connected through the pivoted links 258, 259 with the foot treadle 260, as clearly shown in Fig. 52 of the drawings. This treadle 260 is attached to the shaft 261 extending longitudinally of the machine and supported when in its operative position upon the floor. The opposite ends of the shaft 261 are connected through arms 262 to brackets 263 on the frame of the machine only one of each of which is shown. By constructing and mounting the treadle 260 in the manner just described, it will be seen that the same may be lifted up from its normal position out of the way for the purpose of cleaning beneath the machine. When raised to its uppermost position the links 258 and 259 bend at their point of pivotal connection with each other and the arms 262 turn on their pivotal connections with the brackets 263. When the treadle is in its operative position, as shown in Fig. 52 of the drawing, it will be noted that by depressing the inner end thereof the crank 257 will be rocked and the valve 253 opened. The extent of opening movement of this valve is thus under the control of the operator so that the suction acting upon the under side of the die bed 193 within the die 193 may be increased or decreased and accurately regulated. In order to limit the opening movement of the valve 253, however, I secure to the under side of the valve casing 250, a bracket 264 having a set screw 265 in the horizontal portion thereof which lies within the path of movement of the crank 257 and is engaged by said crank when the latter is moved downwardly. By turning the set screw 265 so as to raise or lower the same, it will be obvious that the extent of the opening movement of the valve 253 may be decreased or increased.

The suction acting within the hollow shaft 232 through the nipple 247 and the perforations 251, also acts upon the inside of the roller 194 through the hollow stem 239. To effect this result, that portion of the stem 239 which is located within the roller 194 is provided with perforations 266. It has heretofore been stated that the stem 239 of the roller 194 is mounted to turn in bearings in the outer or free end of the bracket arm 237 and in the lower end of the hub 236. Said stem also communicates with the interior of the hollow shaft 232 by way of the non-rotatable tube 267 whose inner end constitutes the seat for the valve 268. The said tube 267 is secured to the hollow shaft 232 in line with the stem 239 and closely abuts against the adjacent end of said stem. The valve 268 which is adapted to seat against the tube 267 is provided for regulating the suction on the inside of the roller 194. This is done by increasing or decreasing the distance between said valve and the inner end of the tube 267, which operation of the valve is effected automatically by the means now to be described. The said valve 268 is fulcrumed at 269 to the inner wall of the hollow shaft 232 and is connected through the link 270 with a lever 271 fulcrumed upon a bracket 272 on the outside of the hub 236 of the bracket arm 237. The lower end of the lever 271 carries a roller 273 which moves in contact with a cam 274 formed upon or secured to the hub of the fixed gear 240. The said roller is retained in contact with said cam by means of the spring 275 which is connected to the hub 236 and bears against

the outer side of the lever 271 at a point intermediate of the ends of the latter. Now, it will be observed that during the rotation of the hub 236 and the hollow shaft 232, the 5 free end of the lever 271 will be moved outwardly and inwardly in accordance with the irregularities in the curvature of the cam 274 against which the roller 273 on said lever bears. When the lever 271 is moved 10 outwardly away from the shaft 232, it will obviously move the valve 268 in the same direction, and separate the same from the tube 267. The full force of the suction in the hollow shaft 232 may then act through the 15 stem 239 and perforations 266 upon the inside of the roller 193. When the lever 271 is moved in the opposite direction, the valve 268 will be moved in the same direction toward the tube 267. The mouth or entrance 20 to said tube will therefore be contracted to an extent corresponding to the degree of approach of the valve 268 to said tube, and the suction from the hollow shaft 232 through the stem 239 and perforations 25 266 on the inside of the roller 193 will be correspondingly decreased. The object of this automatic control of or variation in the suction on the inside of the roller will presently appear.

30 *Wrapper carrying and feeding mechanism.*—The roller 194 cooperates with the die 193 to cut the tobacco leaf on the latter into the proper shape for the wrapper, and simultaneously, with the cutting, takes it up 35 from the die and delivers the same to the wrapper carrier 191. The said wrapper carrier shown in detail in Figs. 19-18, consists of a frame preferably made of the two parts 276, 277, a traveling wrapper feeder 40 or apron 278 thereon, the rollers 279, 280 to which the ends of said feeder are attached and a guide roller 281 around which the intermediate portion of the feeder passes. The said feeder has imparted to it a movement 45 over the upper surface of the carrier 191 at a variable speed, and said carrier is adapted to be moved longitudinally of the wrapper-applying rolls 190 and to swing during such longitudinal movement so as to 50 change the angle at which it presents itself to said rolls 190. Said carrier is also adapted to be moved upwardly and downwardly. The part 276 of the frame of the wrapper carrier 191 is formed with parallel sides 282 55 and with a suction box 283 at its upper end. The said suction box extends throughout the length of the part 276 and has an opening in its upper wall across which extend the parallel slats or strips 284, and on these slats 60 or strips are supported the longitudinally extending parallel wires 285 (Fig. 43). The said slats and wires constitute a support for the wrapper feeder 278 which moves thereover and prevent any sagging 65 thereof. They also allow the suction in the

suction box 283 to act upon the under side of the feeder 278 and through the perforations 286 in said feeder on the wrapper when disposed on its upper surface. The arrangement of the series of perforations 286 in the wrapper feeder 278 is such as to correspond in outer contour with the wrapper cut by the die 193 and with the perforations 227 in the roller 194. The rollers 279, 280 are secured to shafts 287, 288 extending 70 parallel to each other at one end of the wrapper carrier frame, and mounted in suitable bearings in the sides 282 of the part 276. The said shafts are provided with intermeshing gears 289, 290, by means of 75 which the same are rotatable simultaneously and in opposite directions.

Beneath that portion of the suction-box 283 adjacent to the guide roller 281, the part 276 of the carrier frame is provided with a 80 passage 291, Figs. 42 and 47 which is cut off from the other parts of the device. With the opposite ends of the wrapper feeder 278 secured to the rollers 279 and 280, the said 85 wrapper feeder extends from the roller 279 up over the top surface of the part 276 of the carrier frame, thence around the guide roller 281, and thence through the passage 291 along the under side of the suction-box 283 to the roller 280. By this construction 90 the roller 281, the roller 281, 100 operating progressively to cut off suction from the feeding mechanism and thus from the wrapper as the latter is being fed to the wrapper-applying mechanism and to the comb. It will also be observed that by 105 varying the speed of rotation of the rollers 279 and 280, a variable speed of movement will be imparted to the feeder or apron. While moving in the manner described, the 110 feeder is supported without danger of sagging upon the wires 285 and the wrapper thereon is subjected to the action of the suction within the suction-box 283. Secured to the part 276 of the carrier frame and communicating with the chamber 292 within the 115 same, is a hollow nipple or coupling piece 293, to which it is intended to attach a suction pipe communicating with a suction fan or other suitable exhausting device. The chamber 292 is closed at its top, bottom and ends with the exception of the opening through which the nipple 293 is connected, but is provided with openings 294 in its sides. The end of the suction-box 283 which 120 is formed above the chamber 292 is also provided with openings 295 in its sides, the same communicating, as will presently appear, with the openings 294. The forward end of the part 276 of the carrier frame is 125 inclosed by the part 277 thereof, the latter 130

being provided with diagonally arranged openings 296, for the reception of rods or projections 297 on the part 276, for the adjustment of the latter part on the part 277. The inner surface of the sides of the part 277 of the carrier frame are provided with recesses 298 which, when in place, inclose the openings 294 and 295 and form passages between said openings. It will thus be seen that the suction to the nipple or coupling piece 293 acts through the chamber 292, the openings 294, the passages 298, and the openings 295, upon the inside of the suction-box 283, and through the latter upon the wrapper on the upper surface of the feeder 278. Interp 1 between the wrapper-carrier frame and the wrapping mechanism is an element which constitutes a support which engages and supports the wrapper in its passage from the wrapper-presenting or feeding means to the wrapping mechanism. This element, in the example of my invention illustrated in the drawing, is in the form of a hollow suction-plate or box having perforations 300 in its upper wall and communicating through the passages or openings 301 with the passages or recesses 298, heretofore referred to. Through the passages 298 and 301, the suction from the chamber 292 acts within the suction plate 299 in an obvious manner. The suction plate 299 constitutes the delivery end of the wrapper carrier and is of course located in comparatively close relation to the wrapper-applying rolls 190. The end of the wrapper passes over the suction plate 299 as it is delivered to the rolls 190, and cooperating with said plate at the time when the wrapper is first being delivered, is a stationary suction plate or box 302 located on the opposite side of the cluster of wrapper-applying rolls 190. The said suction plate is of substantially the same construction as the suction plate 299, the same being hollow and provided with perforations in its top wall. The same is carried by the hollow pipe 303, which is adjustably supported on the frame of the machine and communicates in any suitable manner with an exhausting device. The element 299 constitutes an intermedium between the wrapper-presenting or feeding means and the wrapping mechanism to support the wrapper in its passage and avoid undue stress upon the latter. In the performance of this office, it may, or may not, be a suction-plate or box, as shown. When in the form of a suction-plate or box it performs the other offices specified. In the aspect of my invention, as viewed from the feeding means and with respect to the claims made for such feeding means, in combination with cigar wrapping mechanism, such element may, or may not, be used according to the requirements or necessities in given cases.

The frame of the wrapper carrier is pivoted at a point beneath the rolls 190 to provide for the swinging movement of said frame so as to vary the angle at which the said carrier lies to the rolls 190 during the longitudinal movement of said carrier. The said frame is pivoted to a transversely movable slide 304 mounted upon a vertically movable supporting plate 305 (Figs. 1, 2 and 42). To provide for the pivotal connection between said frame and the slide 304, the part 277 of said frame is formed with an extension 306 through the end of which passes the pivot bolt 307 into said slide. Said extension 306 is provided, concentric with the pivot 307, with a depending circular rack or gear 308 which fits within a recess 309 in the slide 304. Said slide 304 (see Figs. 44 to 46) is further provided with a circular recess 310 which intersects the recess 309 and has seated therein a gear 311. The said gear 311 is provided with a central depending stud 312, which constitutes the pivot thereof and fits within a correspondingly shaped opening in the said slide. The gear 311 is further provided with an eccentric stud 313 fitting and moving within a segmental slot 314 in the slide 304. The said slide 304 has a dovetailed connection with the supporting plate 305 and is also provided with a laterally extending arm 315, by means of which it is moved transversely of the machine in the direction of the length of the rolls 190. Secured to the upper surface of the supporting plate 305 and fitting within a recess in the lower surface of the slide 304 is a plate 316 having an irregularly-shaped slot or groove 317 therein, which is adapted to receive the end of the stud 313 on the gear wheel 311 which projects down through the segmental slot 314 in the slide 304. Said plate 316 is also provided with a straight slot or groove 318 which connects the opposite ends of the irregularly curved slot or groove 317. The said slot or groove 318 extends parallel to the side edges of the plate 316 and to the path of transverse movement of the slide 304. It also is adapted to receive the stud 313 on the gear wheel 311. At the point of intersection of the grooves 317 and 318 at one end of the plate 316, a switch 319 is provided, the same being shown in the form of a pivoted arm adapted to open to allow the passage of the stud 313 from the groove 318 to the groove 317, but being normally closed to prevent the passage of the stud 313 from the groove 317 to the groove 318. At the point of intersection of the grooves 317 and 318, opposite the switch 319, a second pivoted switch 320 is provided similar to the switch 319, but so located and disposed as to open to permit the passage of the stud 313 from the groove 317 to the groove 318, but being normally maintained in such position.

tion as to prevent the passage of the stud 313 from the groove 318 to the groove 317. The normal position of the switches 319 and 320 is shown in Fig. 44.

5 The lateral arm 315 on the slide 304 extends through an elongated slot in the upper free end of an arm 321, secured at its lower end to a rock shaft 322 mounted in bearings in the main frame of the machine and having extending upwardly therefrom an arm 323 having a segmental rack or gear 324 upon its upper end (see Figs. 2 and 42). The said rack or gear 324 is in mesh with a similar gear 325 on the lower end of the arm 15 or lever 326 pivoted at a point intermediate of its ends to the main frame and having a stud or projection 327 on its upper end which fits within a cam groove 328 on a cam 329 secured to the driving shaft 4. By this 20 construction, it will be seen that during the rotation of the shaft 4, a transverse movement will be imparted to the slide 304 and to the wrapper carrier frame carried thereby, through the action of the cam groove 25 328 on the pin 327, which rocks the lever 326, the action of the latter lever on the arm 323 of the rock shaft 322 through the intermeshing gears 325 and 324, and the action of the rock shaft 322 through the arms 321 and 30 315 on said slide 304. As the slide 304 is moved transversely of the machine, it carries with it the frame of the wrapper carrier 191, and the latter has imparted to it a swinging movement on its pivot 307 to vary the angle 35 at which the said carrier lies to the rolls 190. Assuming the parts to be in the position shown in Fig. 44, at the beginning of the transverse movement of the slide 304 in the direction of the arrow in said figure, the 40 stud 313 on the gear wheel 311 will be moved from the position in which it is shown in Fig. 44 along the irregularly curved slot or groove 317. As the irregularities are met with they serve to move the stud 313 in one 45 direction or the other, with the result that the gear wheel 311 to which said stud is attached will be moved variably on its pivot 312. As said gear 311 is rotated, its movement 50 will be transmitted through the gear 308 on the extension 306 of the wrapper carrier frame, so as to swing said frame on its pivot 307 and cause the angle at which the 55 wrapper carrier lies to the rolls 190 to be varied. When the stud 313 reaches the opposite end of the slot or groove 317, the switch 320 is opened and said stud passes into the slot or groove 318 and cannot return past the switch 320 back into the slot or groove 317. On the return transverse 60 movement of the slide 304 therefore, the eccentric stud 313 will move along the slot or groove 318 without causing any rotation of the gear wheel 311 and consequently without causing any swinging movement of the 65 wrapper carrier frame. When the slide 304

on its return movement approaches the switch 319, the stud 313 automatically opens said switch and passes to the position in which it is shown in Fig. 44. From this position of said stud, it is impossible for the 70 same to pass by the switch 319 back into the slot or groove 318.

It will, of course, be understood that the purpose of moving the wrapper carrier transversely of the machine and longitudinally of the rolls 190 and of simultaneously swinging the same on a pivot to vary the angle at which said carrier lies to said rolls, is to enable the wrapper on the feeder 278 to be delivered in proper position to the bunch 75 within the rolls 190 and to compensate for variations in the size or thickness of the bunch to which the wrapper is being applied. The transverse movement of the carrier 191 may be fast, slow or at an irregular 80 speed according to the shape of the particular cigar being made and the speed of transverse movement of said carrier may be varied by merely changing the shape or configuration of the cam groove 328. The extent, speed and regularity of the swinging movement of the wrapper carrier 191 may also be varied according to the shape, size 85 and thickness of the particular cigar being made by merely altering the configuration 90 of the irregular slot or groove 317 in which the stud 313 on the gear 311 moves.

In addition to the transverse and swinging movement of the wrapper carrier 191, I have provided for the intermittent raising and lowering of said carrier bodily. One means by which this may be effected will now be described. Rigidly connected with the supporting plate 305 are the arms 330, (Figs. 1, 2, 22 and 42), which are 100 loosely sleeved upon the shaft 4 and constitute supports upon which the wrapper carrier frame may be swung up and down toward and away from the rolls 190. On the under side of the supporting plate 305 is a 105 rod 331, secured in a pair of juxtaposed ears 332, (one only being shown in Fig. 42) and this rod is engaged by the forked or slotted end of one arm of an angle lever 333 fulcrumed at 334 to a fixed part and having a 110 laterally extending stud or pin 335 on its other arm, which fits within a cam groove 336 in the wheel 5. This cam groove is so shaped and disposed that through the greater portion of the rotation of the wheel 115 5, it will retain the wrapper carrier frame in its lowermost or depressed position, as shown in Fig. 42. Once during each complete rotation of the wheel 5, however, an eccentric portion of the groove 336 will act 120 on the pin 335 carried by the angle lever 333 and serve to elevate the wrapper carrier frame so that the suction plate 299 thereon will occupy a position just above the upper 125 of the cluster of rolls 190. Said frame, how- 130

ever, will be held in this position for but a short time when it is retracted to its low-ermost position.

I have heretofore stated that an irregular speed of movement is imparted to the wrapper feeder 278, the pu: use of which is to deliver the wrapper to the bunch within the rolls 190 at a variable speed to compensate for variations in the shape of the bunch to 10 which the wrapper is applied. As the rollers 279, 280, to which the ends of the feeder 278 are connected are intergeared with each other, it will, of course be obvious that when one of said rollers is rotated a corresponding 15 movement in the opposite direction will be imparted to the other. The shaft 288 carrying the roller 280 is provided upon the end opposite the gear 290 with a bevel pinion 337 (Figs. 1 and 2) projecting beyond the side 20 282 of the carrier frame. Meshing with the pinion 337 is a similar pinion 338 secured to a shaft 339, mounted in bearings in a bracket 340 on one side of the carrier frame. The shaft 339 is connected through the universal 25 coupling 341 with the upper end of an extensible shaft 342, the latter shaft being made in two sections, one of which fits within the other and has a key and groove connection therewith. The lower end of the shaft 342 30 is connected through the universal coupling 343 with a shaft 344 mounted in bearings in the bracket 345 on the main frame and carrying a bevel pinion 346. With the lat- 35 ter pinion meshes a segmental rack or gear 347 on the lower end of a rocking lever 348 fulcrumed at a point intermediate its ends to the main frame of the machine and having a stud 349 at its upper end which fits within a cam groove 350 in the disk 329 on the 40 shaft 4, heretofore referred to. By this construction, it will be seen that during a rotation of the shaft 4, the motion thereof will be transmitted to the feeder 278 to cause the same to move toward or away from the 45 rolls 190 around the rollers 279, 281 and 280. The cam groove 350 has an irregular shape and consequently serves to transmit an ir- 50 regular speed of movement to the feeder 278. The cam groove 350 of course acts upon the stud or pin 349 to rock the lever 348, and the latter, through the gear 347 and pinion 346, transmits its movement to the shafts 344, 342 and 339. The latter shaft, through the pinions 338 and 337 transmits 55 its movement to the shaft 283 of the roller 280, and through the gears 290 and 289, the motion of the latter shaft is transmitted to the shaft 287 of the roller 279. As the frame of the wrapper carrier 191 is movable 60 upwardly and downwardly as well as trans- versely of the machine, and also as a swing- 65 ing movement imparted to it, it is of course obvious that the connections between the pinion 346 and the pinion 338 must, as de- scribed be such as to provide for universal

movement as well as for the lengthening and shortening of the same.

The wrapper-applying rolls 190 are ar- ranged in a cluster and during the opera- 70 tion of the machine are caused to rotate in unison to roll the bunch contained within them and to assist in applying a cap thereto. The said rolls are also capable of bodily movement away from each other in order that they may discharge the com- 75 pleted cigar from within them and receive the bunch from the bunch carrier 156. After the bunch has been introduced within the cluster of rolls, the same automatically close upon said bunch. To provide for 80 these bodily movements of said rolls, the same are mounted upon and carried by the jaws 351, 352, 353 and 354 (Figs. 1, 22, 28, 29, 35, 37, 38, 40 and 41). The jaws 351 and 352 are in line with each other and 85 have mounted therein two of the rolls 190 which for convenience of description, I shall designate by the further reference char- acters D and E, respectively. The jaws 353 and 354 are also located in line with each 90 other and have mounted therein the oppo- site ends of two more of the rolls 190 which, for convenience of description, I shall desig- nate by the further reference characters F and G. The jaws 351 and 353 are located 95 opposite each other and carry the head ends of the rolls referred to, and the jaws 352 and 354 are located opposite each other and carry the opposite ends of said rolls. The jaws 353 and 354 are secured at their lower 100 ends to, and are actuated by, a rock shaft 355 mounted in suitable bearings in the main frame of the machine and extending transversely thereof as shown in Figs. 3 105 and 22. The jaws 351 and 352 are secured at their lower ends to a sleeve 356 which surrounds the rock shaft 355 and is freely movable thereon. The shaft 355 has at- 110 tached to one end thereof a crank arm 357 (Fig. 22) provided with a stud or tooth 358 carrying a roller which fits within a cam groove or raceway 359 in the inner sur- 115 face of the gear wheel 6, heretofore referred to. The sleeve 356 is also provided with a crank arm 360 having an extension with a tooth or projection 361 thereon which fits within a cam groove or raceway 362 in the inner surface of the wheel 6. The cam grooves 359 and 362 are so shaped and dis- 120 posed that they act through the connections described to normally maintain the jaws 351, 352, 353, and 354 in their closed posi- 125 tions, as shown in Figs. 28, 37 and 38. Once during each rotation of the wheel 6, how- ever, which, as heretofore stated, is carried by the shaft 4, the irregularities in the cam grooves 359 and 362 act to open said jaws, as clearly shown in Fig. 29. When said jaws are in their closed positions, the vari- 130 ous wrapper-applying rolls 190 are rotated

and act upon the bunch within them to roll the same and apply the wrapper thereto. When said jaws are opened, however, the bunch secured within them is allowed to drop and they are in position to receive a bunch from the bunch carrier 156.

I have shown and described four rolls as going to make up the cluster of wrapper-applying rolls 190, but this number may of course be increased or decreased as may be found desirable. In addition to the rolls D, E, F and G which are mounted in the jaws 351, 352, 353 and 354, I employ a fifth roll which, for convenience of description, I shall designate by the additional reference character H. This roll H is carried by the jaws 353 and 354, but the opposite ends of the same are mounted in the spring arms 363, 364, (Figs. 28 and 37) each of said spring arms being forked at its lower end to provide two branches. The branch 365 of the arm 363 is secured at its lower end to the jaw 353, whereas the other branch 366 of the arm 363 is free but extends inwardly toward the jaw 351. The branch 367 of the arm 364 is secured at its lower end of the jaw 354, whereas the branch 368 of the arm 364 extends inwardly toward the jaw 352. The tendency of the spring arms 363 and 364 is to elevate the roll H and move the same away from the remaining rolls D, E, F, and G, which go to make up the cluster. This position of the roll H is clearly shown in Fig. 29. Said spring arms 363 and 364, however, are adapted to be moved downwardly so as to cause the roll H to approach the remaining rolls of the cluster, by means of the arms 369, 370, (Figs. 28 and 37) secured respectively to the jaws 351 and 352 and extending outwardly toward the opposite jaws within the paths of movement of the branches 366 and 368 of the spring arms 363 and 364, respectively. That is to say, when by the means described, the jaws carrying the rolls D, E, F and G are caused to approach each other the free ends of the branches 366 and 368 of the spring arms 363 and 364 are caused to engage the free ends of the arms 369 and 370, as shown in Figs. 28 and 37. This action flexes the spring arms 363 and 364 and causes the roll H to assume its proper position down adjacent to the remaining rolls D, E, F and G of the cluster. When, however, the jaws in which the rolls D, E, F and G are mounted are separated from each other, the branches 366 and 368 of the spring arms 363 and 364 are freed from their engagement with the arms 369 and 370 and said spring arms with the roll H carried thereby are moved upwardly to the position shown in Fig. 29, separating the roll H from the remaining rolls D, E, F and G of the cluster.

Each of the rolls 190 is made up of a

rigid core 371 of metal or other suitable material, which is bent or curved to conform to the shape of the cigar being made, but is provided with a straight portion adjacent to one end. Surrounding the straight portion of each of the cores 371 is a tube or sleeve 372 having a pinion 373 thereon. Secured to the sleeve 372 of each of said rolls and surrounding the core 371 are two coil springs 374, 375. The spring 374 is located within the spring 375 and moves in contact with the curved portion of the core 371. As both of said springs, however, are secured to the sleeve 372, they are, during the rotation of said sleeve, rotated together about the core 371. Secured to and surrounding the outer spring 375 is a cover 376 of rubber or other like yielding material, which projects at its inner end beyond the sleeve 372. This cover 376 constitutes the working face of each of the rolls, and being of yielding material itself, and being mounted upon two yielding springs 374, 375, it constitutes a working surface well adapted to the purpose for which it is designed. The cores 371 of the rollers D and E are secured at their opposite ends respectively to the jaws 351 and 352, the cores 371 of the rolls F and G are secured at their opposite ends respectively to the jaws 353 and 354, and the core 371 of the roll H is secured at its opposite ends to the spring arms 363 and 364. For rotating the various rolls 190, I provide a shaft 377 (Fig. 22) mounted in suitable bearings in the main frame of the machine, the said shaft being made hollow, for a purpose which will hereinafter appear. One end of said shaft is provided with a pinion 378 which meshes with the teeth of the gear wheel 5 by which said shaft is continuously rotated, and the opposite end of said shaft is provided with a pinion 379 which is adapted to mesh with the pinions 373 on the sleeves 372 of each of the rolls 190, when the latter are in their closed positions. The said pinions are shown in gear with each other in Fig. 37. It will be noted, however, that when the jaws by which the rolls 190 are carried are separated from each other the pinions 373 move away from and out of mesh with the continuously rotating pinion 379. The rotation of the rolls 190 is therefore arrested. By the gearing described, all of the rolls 190 are rotated in the same direction and all consequently serve to rotate the bunch within them in the proper direction for applying the wrapper thereto.

The head ends of the rolls D, E, F and G terminate adjacent to the jaws 351 and 353, by which they are carried. The roll H, however, is extended at its head end so that it is longer than the remaining rolls of the cluster, this increased length of the roll H being provided for a purpose which will

hereinafter appear. To receive the extended end of the roll H, the jaw 353 is provided with a recess 380 (Fig. 41) in its upper end in which the head end of the roll H is adapted to fit when in its lowermost operative position. The upper end of the jaw 353 is also slightly recessed, as shown at 381, (Fig. 38) for the reception of the head end of the bunch, to which the wrapper is being applied from around the roll H. When the jaws by which the various rolls 190 are carried are separated, the roll H is lifted from its normal position in the recess 380, but when said jaws are closed, said roll H is automatically returned to its position within said recess. The said roll H performs a very important function in the operation of applying the wrapper to the bunch, which will be more fully brought out in the description of the operation.

Tip cutting and nicking mechanism.—As the wrapper is being wound upon the bunch in the rolls 190 and approaches the head end of the bunch, it is important that said wrapper be again cut in order to secure the proper length and shape of wrapper for the head of the cigar, which will prevent the formation of any projecting portions at the tip. To accomplish this result, I provide the coöperating cutters 382 and 383, (Figs. 28, 29, 30, 31, 34, 35 and 36) and what I term a nicking blade 384. The cutter 383 is secured to a rocking support or bracket 385, and the cutter 382 is secured to a reciprocating slide or slide-block 386. The two cutters 382 and 383 coöperate with each other, the same being in the form of curved blades, shaped to conform to the cut which it is desired to make at the rear end of the wrapper. The support 385 is provided with a bearing sleeve 387 which surrounds a bearing sleeve or hollow projection 388 formed on the bracket 389 (Figs. 35 and 36) secured to the main frame of the machine.

The bearing sleeve 387 has extending outwardly from it a crank arm 390 (Fig. 31) which is pivotally connected through the link 391 (Figs. 34 and 35) with a crank arm 392 on the rock shaft 355, heretofore referred to. By this construction, it will be seen that when the shaft 355 is rocked in its bearings for the purpose of opening or separating the rolls 190 from each other, the bracket 385 and the parts carried thereby will be rocked on the bearing sleeve 388 in the same direction that the jaws 353 and 354 are moved, so as to swing said bracket out of the path of movement of the bunch carrier 156, as the latter approaches the cluster of rolls 190 for the purpose of depositing a bunch therein. Likewise, when the shaft 355 is rocked to return the rolls 190 to their closed positions the bracket 385 will be rocked on the bearing sleeve 388 to return the same to its normal vertical position. The upper end of the bracket 385 is formed with a rectangular head or enlargement 385^a, which fits within a longitudinal passage in the slide 386 and forms a bearing for said slide in its reciprocating movements. Reciprocating movement is imparted to said slide 386 through a shaft 392^a, (Fig. 36) having bearings in a sleeve 393 on the bracket 385 and provided with a disk 391, on its inner end, the said disk having a crank-pin 395 thereon which fits and moves within an elongated transverse slot 396 (Fig. 39) in the slide 386. Intermittent rotary movement is imparted to the shaft 392^a through the pinions 397, 398 and 399. The pinion 397 meshes with the peripheral teeth on the wheel 6, and also meshes with the pinion 398. The latter pinion is secured to a sleeve 400 which extends through and has bearings in the bearing sleeve 388, heretofore referred to. The pinion 398 also meshes with the pinion 399, and the latter pinion is loose upon the shaft 392^a and forms one member of a clutch between the pinion 398 and said shaft. The other member 401 of the clutch is splined upon the shaft 392^a and is capable of longitudinal movement thereon. The member 401 of the clutch is provided with a longitudinally extending pin 402 at its inner end, which when said member is projected inwardly, is adapted to fit within one or the other of a series of notches or recesses 403 in the outer surface of the pinion 399. The clutch member 401 is also provided with a peripheral groove 404 within which fits a fork 405 on one arm of a lever 406 which is secured at a point intermediate of its ends upon a bracket arm 406^a on the bracket 385. The other arm of said lever 406 is adapted to be engaged by the upper arm of a lever 407 secured upon a bracket 408, fixed to the frame, and carrying a roller or projection 409 at its opposite end, which moves within a cam groove 410 in the periphery of the wheel 6. The cam groove 410 is so shaped and disposed that once during each complete rotation of the wheel 6 it acts to rock the lever 407. When so rocked, the upper end of said lever 407 acts upon the lever 406 to rock the same upon its pivot, and to move inwardly the forked end 405 thereof. When the lever 406 is thus operated, the clutch member 401 is thrown into coöperative relation with the clutch member or pinion 399, with the result that the shaft 392^a will be locked to the pinion 399, will be rotated thereby, and through the crank pin 395 thereon will bring about a reciprocating movement of the slide 386. When the latter movement takes place the cutter 382 will be moved toward and away from the cutter 383, and the rear end of the wrapper, as it is being fed to the head end of the cigar, will be squared off when the

wrapper is completely wound upon the cigar it will exactly fit at the head. The nicking blade 384 is also secured to the slide 386, and is disposed in a plane at right angles to the bunch within the rolls, and during the reciprocating movement of the slide the blade acts to nick the wrapper at the extreme tip of the bunch, so as to prevent the formation of a teat or projection by the wrapper at the head end of the completed cigar. The cutters 382 and 383, act upon the wrapper but once, the cut produced thereby, in conjunction with the nick made by the blade 384, shaping the rear end of the wrapper so that when it is wound upon the head end of the bunch it will exactly fit without any projecting or overlapping portions.

Paste-applying mechanism.—Secured to the overhanging portion of the rocking bracket 385, projecting downwardly therefrom and communicating with a cylindrical passage 411 in said bracket is a pipe or tube 412, (Fig. 36) the said passage and the said pipe or tube being provided for the reception of a paste-ejecting plunger 413 carried by the slide 386. Communicating with the passage 411 is an inclined port or passage 414 through which paste is supplied from the paste receptacle 415, supported upon a bracket 416 on the main frame of the machine above the jaw 351. The said receptacle 415 is provided on the inside thereof with a downwardly spring-pressed piston 417, (Fig. 22) by means of which the paste is caused to flow from said receptacle through a pipe 418 and thence through the port 414 into the passage 411. This flow of paste is, of course, assisted by gravity. During the reciprocation of the slide 386 the plunger 413 is moved back and forth in the passage 411, causing the paste at the lower end thereof to be ejected from the pipe or tube 412. The said pipe or tube 412, however, registers with a port 419 (Figs. 38 and 41) in the jaw 351, when the cluster or wrapper applying rolls 190 are in their closed position, the said port 419 discharging at the head end of the cigar within said rolls, so that the paste from the receptacle 415 is delivered at just the point where it is needed.

Wrapper tucking mechanism.—The tucking needle 192 (Fig. 23) is designed to engage the forward end of the wrapper which is delivered from the carrier 191 onto the suction plate 302, to move the same down into contact with the bunch within the rolls 190, and to retain the same in contact with said bunch until more than one revolution of the latter has been effected by said rolls. The said needle is constructed of spring wire or other like flexible material and extends freely through a sleeve 419^a, longitudinally movable within the hollow shaft 377, herebefore referred to. The outer end of the

needle 192 is adjustably secured within the bracket or frame 420, (Fig. 22) having a depending stud or projection 421 thereon which fits within the cam groove 422 in the periphery of the wheel 5. The groove 422 is so disposed that during the rotation of the wheel 5, it will impart a longitudinal movement to the needle 192 toward and away from the bunch within the rolls 190. To provide for the adjustment of the needle 192 in the bracket 420, the latter is formed with an opening in which fits two clamping members 423, 424. The clamping member 423 has a tapering opening therein, and the body of the member 424 is correspondingly shaped and fits within said opening and both members are split longitudinally. A screw threaded connection is provided between these two clamping members so that when one is screwed within the other, the member 424 will be moved into gripping contact with the needle 192 and the member 423 will be moved into gripping contact with the inner surface of the opening in the bracket 420. It will be obvious that by loosening or separating the members 423, 424 from each other, the needle 192 may be moved in one direction or the other in the member 424 and the position of the same thereby adjusted. Adapted to engage the underside of the needle 192 adjacent to the tuck end of the bunch within the rolls 190, is a forked lever 425, fulcrumed at its lower end to a bracket arm 426, secured to the frame of the machine. At a point intermediate its ends, said lever is pivotally connected, through the links 427, (Fig. 27) with the inner end of the sleeve 419^a. The fork 428 in the lever 425 is formed in its upper free end and is adapted when moved upwardly to receive the needle 192 and move said needle upwardly with it. Longitudinal movement is imparted to the sleeve 419^a, by means of a stud or projection 429 thereon, (Fig. 22) which fits within a cam groove or raceway 430 in the periphery of the wheel 5. As the projecting end of the wrapper is delivered upon the suction plate 302, above the tuck end of the cigar, the inner or free end of the needle 192 is in its raised position, the said needle having been raised by the retraction or outward movement of the sleeve 419^a due to the action of the cam groove 430 on the stud or projection 429. When said sleeve 419^a is moved to its outermost position, the forked lever 425 is rocked on its fulcrum and the free end thereof is elevated. Said free end, however, engages the under side of the needle 192 and raises the same with it. While the needle is above the projecting end of the wrapper, the cam groove 430 acts to move the sleeve 419^a in the opposite direction or toward the bunch within the rolls 190. The free end of the needle 192 is therefore released and allowed

to move downwardly into contact with the tuck end of the bunch, carrying with it the projecting end of the wrapper and embeds itself into the outer side of the bunch, as shown in Fig. 25, thus to obviate any contact with the wrapper-applying rolls. The bunch is at this time being rotated by the action of the rolls 190 and the end of the wrapper is held in contact with the bunch until the latter has moved more than one complete revolution, that is, until the wrapper is wound so that the free end thereof is covered and held in place by an intermediate portion of the wrapper. The cam groove 422 now acts automatically on the stud or projection 421 to move the bracket 420 and the needle 192 secured thereto outwardly away from the tuck end of the bunch. The free end of said needle is therefore disengaged from both the wrapper and the bunch, but as soon as it is withdrawn from this position, it is re-inserted, into the center of the tuck end of the bunch, as shown in Fig. 22, the inward movement of said needle in a direct longitudinal line being effected automatically by the action of the cam groove 422 on the stud or projection 421.

Figs. 23 and 24 show the free inner end of the needle 192 in its raised position above the projecting end of the wrapper on the suction-box 392, just prior to the depression of said needle to move said wrapper into contact with the bunch. Fig. 25 shows the needle after it has been depressed to carry the projecting end of the wrapper down upon the outer surface of the bunch and between the rolls 190. Fig. 26 shows the position of the wrapper when the needle 192 is withdrawn from its engagement therewith. That is to say, in the latter figure, the bunch has been turned so as to wind the wrapper on the tuck end thereof a little more than one complete revolution.

Tip polishing mechanism.—After the wrapper has been completely wound upon the bunch from the tuck end to the tip thereof, the jaws by which the rolls 190 are carried separate from each other, but the bunch is held independently of said rolls for a short period of time by the needle 192 which projects into the tuck end of the bunch and by an automatically movable gripper 431, which engages the cigar near the head thereof (Figs. 22, 29 and 42). While thus supported, the tip of the head of the cigar is polished by a rotating cup 432 (Figs. 22, 35 and 36) and the opposite end of the cigar is cut by the cutter 433. The cup 432 is secured to the end of a rotary shaft 434 and has the cavity within it shaped to conform to the shape which it is desired to impart to the tip of the cigar. The shaft 434 extends through the sleeve

400, heretofore referred to, and has a spline 65 connection therewith, so that the same is capable of longitudinal movement in said sleeve and at the same time is rotated thereby. The sleeve 400 is rotated by a pinion 435 which meshes with a pinion 436 on the 70 inner end of said sleeve the pinion 435 being carried by the shaft on which the pinion 397 is mounted and deriving its motion from the latter pinion. Within the sleeve 400, the shaft 434 is provided with a shoulder, and is surrounded by a coil spring 437 which acts on said shoulder and also on a shoulder on said sleeve, to urge said shaft and the cup 432 carried thereby to its rear-most position, away from the tip of the 80 cigar within the rolls 190. The outer end of the shaft 434 is acted upon by an inwardly-facing serrated segmental flange 438 on the wheel 6 as shown in Figs. 1 and 22. For a short interval during the rotation of 85 said wheel 6, therefore, an intermittent longitudinal movement will be imparted to the shaft 434 and to the cup 432 carried thereby, which will cause the same to approach and recede from the head of the cigar. A continuous rotary movement is imparted to said cup through the gearing above described. The shaft 434 and the cup 432 carried thereby are, of course, rotated in the same direction in which the wrapper is applied to the 90 bunch, and the serrations on the flange 438 are so arranged thereon, that, during the time that the wrapper is being applied and the rolls 190 are in their closed position, the cup 432 will be held away from the tip 100 end of the cigar. When, however, the gripper 431 has been moved upwardly to support the head end of the cigar, and the jaws carrying the rolls 190 have been moved away from each other, the serrations on the 105 flange 438 act to move the shaft 434 and the cup 432 inwardly toward the head of the cigar. The said cup is at this time being rotated by the means described, and is brought into engagement with the tip of the 110 cigar, the latter fitting within the cavity in said cup. While still rotating, it is caused to approach and recede from the cigar somewhat rapidly so as to polish the tip of the 115 cigar and make the heads of all of the cigars of uniform shape.

It will be understood, of course, that the spring 437 acts to move the shaft 434 and the cup 432 in opposition to the serrations on the flange 438. Said spring also acts to 120 rock the lever 406 to disengage the clutch members 401 and 399, when the lever 407 ceases to act on the lever 406 and when the end of the shaft 434 is moved upon an un-serrated portion of the flange 438. To 125 effect this result the lower arm 439 of the lever 406 is provided with an enlarged opening through which the shaft 434 passes,

and said shaft 434 is provided with a lateral pin or projection 440 (Fig. 35) adapted to engage said arm 439 of the lever 406.

Gripping mechanism.—The gripper 431 is made up of a pair of jaws pivoted to each other near their upper ends and having concave inner surfaces shaped to conform to the cross-sectional contour of the cigar being made. Said jaws have depending from them and straddling the sleeve 356, the arms 441, which are pivoted at their lower ends through the links 442 to a vertically movable rod 443. The said rod extends freely through the opening in a lateral arm 444, (Fig. 22) on a slide 445 and has a cross pin or stop 446 thereon, adapted to engage the under side of said arm. Surrounding said rod 443, engaging a shoulder 447 thereon at its upper end and the upper surface of the arm 444, is a coil spring 448, which operates as a yielding gripper closing device, as will presently appear. The cutter 433 is made up of a pair of jaws having cooperating cutting edges 449, adapted to be moved toward and away from each other, the said jaws being pivoted to each other near their upper ends and having depending therefrom the arms 450, which are pivotally connected at their lower ends, through the links 451, to the vertically disposed rod 452. The said rod passes freely through an opening in the arm 452^a (Fig. 22) on the slide 445 and through an opening in a lateral arm 453 on a slide 454. The lower end of the rod 452 is provided with a head 455 and surrounding said rod and engaging said head and the under side of the arm 453 is a coil spring 456, the said spring serving as a yielding support for the slide 454 from the rod 452. The slide 454 is mounted to move in ways in the beam 457 forming part of the main frame, and carries the common pivot 458 for the jaws of the gripper and cutter, and said slide is provided with a stop or projection 459 on its rear side, adapted to engage the lower edge of said beam. The slide 445 is adapted to move in ways 460 (Fig. 42) on the slide 454 and has pivoted to it and leading downwardly therefrom a pitman 461, by means of which reciprocating up-and-down movement may be transmitted thereto. The said pitman has pivoted to its lower end a lever 462, fulcrumed at a point intermediate of its ends to a stationary part of the machine, and carrying a tooth or projection 463 at its opposite end, which fits within a cam groove or raceway 464 in the inner surface of the wheel 5. This groove or raceway 464 is so disposed that, during the greater part of the revolution of the wheel 5, it will act to retain the slides 445 and 454 and the gripper 431 and cutter 433 carried thereby in their lowermost positions, as shown in Fig. 42. Once during each complete rotation of said wheel 5, however, these parts are

raised to the positions shown in Fig. 22, moving the gripper 431 upwardly so that it receives and supports the cigar, and moving the cutter 433 to its raised position and actuating the same to clip the tuck end of the 70 cigar. When the eccentric portion of the cam groove 464 acts upon the pin 463, that end of the lever 462 which carries said pin is moved downwardly and the opposite end, to which the pitman 461 is pivoted, is moved 75 upwardly. When said pitman is raised, it also raises the slide 445, and when the slide 445 rises, it lifts with it the lower parts of the gripper 431 and the cutter 433, the latter being engaged by the arm 452^a which moves 80 in contact with the shoulder on the rod 452. As the rod 452 is raised, it carries with it, the slide 454 which is supported from the head 455 on the rod 452 by the stiff spring 456 and the slide 454 lifts the upper parts of 85 the gripper and cutter. During the upward movement of the gripper 431 and the cutter 433, no action whatever takes place upon the jaws of which said parts are made up. In other words, said jaws at their upper 90 ends are held in their open positions. When, however, the gripper 431 reaches the cigar upon which the wrapper has just been wound, its upward movement is resisted by the stop or projection 459 coming in contact 95 with the beam 457. The slide 445, however, continues its upward movement and compresses the spring 448, with the result that through the links 442, the lower ends of the arms 441 of the gripper jaws are separated, 100 and said jaws themselves are caused to engage and tightly retain the cigar held between them, the spring 448 operating to prevent such positive contact between the gripper jaws and the cigar as would tend to 105 crush the latter. When also, the stop or projection 459 comes in contact with the lower edge of the beam 457, the upward movement of the slide 454 is arrested, but the slide 445 continues its upward movement. The result is that the spring 456 is compressed and, through the links 451, the lower ends of the arms 450 of the cutting jaws are separated or spread apart, causing the upper end of said jaws on which the 115 cutting edges 449 are formed to approach each other and sever the tobacco at the tuck end of the cigar. During the upward movement of the cutter 433, the tuck end of the cigar is supported by the needle 192, which 120 has previously been introduced centrally into the cigar. Just before the cutter is actuated, however, to clip the cigar at the tuck end, the cam groove 422 will have acted upon the stud or projection 421 to automatically move the inner end of said needle out of the tuck end of the cigar. The cigar is now in its finished condition, the wrapper having been applied to the bunch, the tip of the head polished and the tuck end cut. 130

When the groove 464, however, acts to return the slide 445 to its lowermost position, the gripper 431 and the cutter 433 are moved downwardly, the jaws of the gripper 431 are separated at their upper ends and the completed cigar is allowed to fall into any suitable receptacle provided for it.

Instead of the coöperating cutters 382 and 383 for cutting the end of the wrapper 10 prior to its application to the head end of the bunch and the nicking cutter 384 for said wrapper, I may employ coöperating cutters 465 and 466 (Fig. 40) for cutting the head end of the cigar, or the projecting 15 wrapper at the head end of the cigar, after the wrapper has been completely applied. The cutter 465 is in the form of a cutting blade secured to the heading jaw 351, and has a circular opening 467 into which the 20 tip of the bunch or cigar is adapted to fit. The cutter 466 is in the form of a blade secured to the heading jaw 353 and coöperating with the blade 465. The opening 467 in the blade 465 may be increased or decreased 25 in size to adapt the device for the formation of cheroots or cut-head cigars, or said opening may be so small as to adapt the device for merely clipping the projecting end of the wrapper at the extreme tip 30 of a pointed-head cigar. The blades 465 and 466 are so disposed with respect to each other that when the jaws carrying the rolls 190 are closed, a free passage through the opening 467 will be exposed for the reception 35 of the tip of the bunch. When, however, the jaws which carry the rolls 190 are separated from each other, the cutting edges of the blades 465 and 466 will act upon the head end of the cigar to cut the same, in 40 an obvious manner.

Prior to the operation of the machine, it will be understood, of course, that the cutting edge of the die 193 will be made to correspond with the size and shape of the 45 wrapper to be formed. The outer contour of the series of perforations 286 in the feeder 278 will also be made to correspond to the shape of the die 193. The perforations 286 will be so arranged upon the feeder 278 that 50 when said feeder is at rest and is in its rear-most position, the forward edge of the series of perforations 286 will lie adjacent to the suction plate 299. The roller 194 has the series of perforations 227 therein so arranged 55 that when it is moved over the feeder 278, said series of perforations will exactly register with the series of perforations 286. To effect this result properly it is generally advisable to form the perforations 227 in 60 the roller 194 after the perforations 286 have been formed in the feeder 278, for it will be readily understood that no relative adjustment of these parts can afterward be made. The die 193 then has its position adjusted 65 so that the cutting edge thereof will

register with the outer edges of the series of perforations 227 in the roller 194 when the latter is moved over said die. To accomplish this, the die 193 is mounted, as heretofore described, for longitudinal, lateral 70 and axial adjustment on the bed 195, and the same is also adapted to have the plane of its cutting edge adjusted so that all portions thereof will be engaged by the surface of the roller 194 when the latter moves 75 over it.

During the operation of the machine, the shaft 4 is continuously rotated and by the means heretofore described, a continuous revolving movement is imparted to the roller 80 194 from said shaft. Said roller is thus caused to pass successively over the die 193 and the feeder 278. While passing over said die and over said feeder, a rotary or axial turning movement is imparted to said roller. 85 Just before the roller 194 reaches the die 193, a tobacco leaf is placed upon said die by the operator, and the treadle 260 is depressed, which action opens the valve 253 and permits the suction to act upon the under side of said leaf through the perforations 214 in the die-bed 213. The said leaf is thereby firmly held in place upon the die in a flattened condition. The degree of suction may be accurately controlled by opening 90 the valve 253 to a greater or less extent. As a matter of fact, while the roller 194 is passing over said die, the valve 253 is held but partially open so that the suction acting upon the under side of the leaf is less than 95 that acting within the roller 194. The said roller upon reaching the die coöperates with the cutting edge thereof to sever the leaf along said cutting edge to produce a wrapper of the desired shape. At the same time, 100 it lifts the wrapper as it is cut from the die 193, the same being caused to adhere to said roller by reason of the fact that the suction within said roller is greater than that within said die. The wrapper when it is lifted 105 from the die 193 by the roller 194 adheres to the latter without the formation of wrinkles or creases therein and is held upon said roller in exactly the same shape in which it was cut. While passing over the 110 die 193, the pinion 241 on the stem 239 of the roller 194 is in mesh with the teeth of the mutilated gear 240 and an axial turning movement is imparted to said roller. This turning movement, however, ceases as soon 115 as the roller 194 passes from the end of the die 193, as at that time the pinion 241 passes into the mutilated portion of the gear 240 and the presser block 245 comes into engagement with the flat portion of the collar 120 244. During this time the suction is acting through the coupling piece 293, the chamber 292, the passages 298 and the suction-box 283 upon the under side of the feeder 278. At the same time the carrier 191 is being 125 130

removed or has been moved to its raised position, with the suction plate 309 carried thereby located at a point adjacent to and above the roll 11 of the cluster of rolls 190. This elevation of the wrapper carrier is effected by the action of the eccentric portion of the cam groove 336 on the stud or projection 323 of the lever 333, which lever is connected through the rod 331 with the under side of the plate 305 on which the wrapper carrier frame is supported.

As the roller 191 continues its revolving movement from the die 193 to the carrier 191, with the wrapper adhering to the surface thereof, the suction within said roller 194 is automatically decreased by reason of the fact that as the roller 273 on the lever 271 moves into contact with the lower portion of the cam 274, said lever is moved inwardly by the spring 275 and the valve 268 is moved toward the tube 267 through which the suction passes to the inside of the stem 269 and thence through the perforations 266 to the inside of the roller 194. When said roller 194 reaches the carrier 191, therefore, the force of the suction beneath the feeder 278 is greater than that within said roller. Consequently, when contact takes place between the roller 194 and the feeder 278, or rather between the wrapper on said roller 194 and said feeder, the said wrapper is gradually released from the roller 194 through the action of the suction beneath the feeder 278 which is of greater force than that within the roller 194. The result is that after said roller passes beyond the carrier 191, the wrapper will have been removed therefrom and will be found adhering to the feeder 278, with the outer edges thereof registering with the outer edges of the series of perforations 286. When the roller 194 passes over the wrapper carrier 191, the said carrier is in its raised position and the wrapper is delivered to the feeder 278 thereon in a flattened condition and stretched both longitudinally and laterally. At this time, the carrier 191 is also in the position shown in Fig. 1; that is to say, it is located at one end of its stroke transversely of the machine with the suction plate 309 lying adjacent to the tuck end of the bunch within the rolls 190. After receiving the bunch from the bunch carrier 190, the rolls 190 close upon said bunch, as shown in Figs. 2A, 2B, 2C and 42, and said bunch is rotated by said rolls. The projecting end of the wrapper on the carrier 191 is received by the stationary suction plate 302 when said carrier is in its raised position, but as soon as the wrapper has been thus delivered upon the suction plate 302, the carrier 191 is moved to its lowest position, as shown in Fig. 3A, drawing the wrapper over the upper surface of the upper roll 11 of the cluster of rolls

190. At the same time, or just after the carrier 191 returns to its lowest position, the tucking needle 192 which has previously been raised to a point above the wrapper on the suction plate 302 by the means heretofore described, is released and acts to force the projecting end of the wrapper down onto the bunch within the rolls 190. As said bunch is at this time revolving, the wrapper is fed while still held in place on the bunch by the needle 192, from the carrier 191 and wound upon the bunch at the tuck end thereof. Of course, during this time the wrapper is being fed by the movement of the feeder 278 to the rolls 190. After the wrapper has been wound upon the bunch a little more than one revolution, or until it is capable of holding itself in place, the needle 192 is moved outwardly through the action of the cam groove 422 on the stud or projection 421, thus to separate and disconnect said needle from both the wrapper and the bunch. Almost immediately, however, the needle 192 is moved in the opposite direction to cause the same to be re-inserted into the center of the bunch at the tuck end thereof. This insertion of the needle into the bunch serves still further to assist in the creation of a free draft through the completed cigar and also serves, as has been heretofore stated, to support the bunch after the rolls 190 have been disengaged from the bunch. It will be noted that all of the rolls D, E, F, G and H which go to make up the cluster of rolls 190 are rotated in the same direction. They will, consequently, act to rotate the bunch contained within them in the opposite direction. The wrapper which is fed to the bunch passes around the roll H, which roll is rotating in a direction opposite that of the feed of the wrapper to the bunch. This roll, it will be remembered, is shaped to conform to the shape of the cigar being made and extends at its head end beyond the other rolls, the same being received in a recess 320 in the upper end of the jaw 358. Said roller, therefore, acts to stretch the wrapper both longitudinally and transversely as it is being fed to the bunch and to create a friction thereon which enables the same to be smoothly applied to the outer surface of the bunch. It also acts to remove all wrinkles or creases in the wrapper and by the friction created thereby to force the oily substance within the wrapper to the surface thereof. By this means, a smoothly applied un-wrinkled polished wrapper may be wound upon the bunch by the rolls 190. This is an important feature of my invention, and one upon which special stress is desired to be laid.

While the roll H has been shown as the one which performs the functions above described, I do not desire to limit myself to the use of one of the rolls 190 as the means for stretching, smoothing and creating a fric-

tion upon the wrapper as it is being delivered to the wrapper-applying rolls. It is obvious that in lieu of a roll forming part of a cluster of rolls by which the wrapper is applied, I may use an independent roll for this purpose, or in fact, a stationary part shaped to conform to the cigar being made and over which the wrapper is caused to pass on its way to the wrapper-applying rolls, it being, of course, essential that the particular means employed be such as to create a friction or tension upon the wrapper. As the rolls 190 continue to rotate and to turn the bunch within them, the wrapper is fed at a variable speed thereto by the movement of the feeder 278 at a variable speed. At the same time, the wrapper carrier as a whole is moved transversely of the machine and longitudinally of the rolls 190 and turned so as to vary the angle at which said carrier lies to said rolls. The irregular speed of delivery of the wrapper to the bunch caused by the irregular speed of movement of the belt or apron 278 is to compensate for variations in the thickness of the bunch to which the wrapper is being applied, it being obviously necessary to feed the wrapper at a higher rate of speed when it is being wound upon a thick portion of the bunch than when it is being wound upon a narrow portion of the bunch. The changing of the angle at which the carrier lies to the rolls 190 to vary the angle of presentation of the wrapper to the bunch so that it may be wound smoothly and evenly on the irregularly curved outer surface of the bunch. Both these operations are effected automatically by the means heretofore described. That is to say, the feeder 278 has imparted to it a variable speed of movement, by means of the irregularly shaped cam groove 350 in the disk 299 which acts through the lever 348, the segmental gear 317 thereon, the pinion 316, the extensible shaft 342, the shafts 341 and 339, which have swivel connections with the shaft 342, the pinions 338 and 337, the shaft 288 carrying the roller 280, to which one end of the feeder 278 is attached, the gears 290 and 289 and the shaft 287 which carries the drum 279, to which the other end of the feeder 278 is attached. The degree of variation in the speed of the feeder 278 may obviously be changed to adapt the device to the manufacture of cigars of different shapes by simply changing the shape or configuration of the cam groove 350. The carrier 191 is moved bodily transversely of the machine by means of the cam groove 328 which receives and acts upon the stud or projection 327 on the lever 326, whose lower end is provided with a gear 325 which meshes with a similar gear 324 on the upper end of the arm 323 on the rock shaft 322. The latter

shaft is thereby rocked and transmits its motion through the arm 321 thereon to the arm or projection 315 on the frame of the carrier. As said carrier is moved from the tuck end of the bunch within the rolls 190 toward the head end thereof, the stud or pin 313 on the gear wheel 311 is caused to pass along the irregularly curved or cam groove 317 of the plate 316, which action turns the gear 311 on its pivot 312, and said gear acting upon the pinion 308 rocks the frame of the carrier 191 on its pivot 307. This causes a variation in the angle at which the said carrier lies to the rolls 190 and consequently changes the angle of presentation of the wrapper to the bunch. By merely varying the shape of the cam groove 328, the speed of transverse movement of the wrapper carrier 191 may be regulated, and by varying the shape of the cam groove 317, the speed and extent of swinging movement of the carrier 191 may be regulated. It will, of course, be necessary to change the shape of these grooves in accordance with the particular shape of the bunch to which the wrapper is applied. When the wrapper carrier reaches the limit of its movement toward the head of the bunch, it passes into the groove 318, where it is held momentarily and then starts upon its return movement to the position which it originally occupied. At the same time, the feeder 278 is moved backwardly to its original position. As the carrier frame is returned to its original position, the same moves in a straight line, as the stud or pin 313 on the gear wheel 311 moves in the straight groove 318. No rotary or turning movement is imparted to the gear 311, therefore, and consequently no swinging movement is imparted to the carrier frame.

While the wrapper is being delivered from the wrapper carrier 191 at an irregular speed of movement and while the angle of presentation of the wrapper to the bunch is being changed, the said wrapper is held by suction on the feeder 278, and consequently, retained in its flattened condition until it passes over the suction plate 299 and around the roll H to the bunch. As soon, however, as any portion of the wrapper passes beyond the suction plate 299, the suction thereon is automatically released and consequently said wrapper is free to be moved or turned in any direction. When the wrapper being thus wound upon the bunch approaches the head end thereof, it is acted upon solely by the upper roll H, which is longer than the remaining rolls and extends into the recess 380 in the jaw 353. Said roll H, therefore, serves to stretch and impart the preliminary shaping to the wrapper throughout the entire length of the bunch to which the wrapper is applied.

When passing around the extended end of the roll 11, the rear end of the wrapper is cut by the co-operating cutting blades 382, 383 so that the wrapper is so shaped as to 5 exactly fit the head end of the bunch when wound upon it. The shape of the cutting blades 382 and 383 may of course be varied according to the particular shape of the head of the cigar being made. Said wrapper is also acted upon at the same time by the nicking blade 384, which serves to cut out a portion of the wrapper so that no projecting end will be left at the extreme tip of the head. These cutters are automatically operated by the means heretofore described. Simultaneously with the operation of the cutters 382 and 383, the plunger 413 acts to eject through the pipe or tube 112 and the port 419 a sufficient quantity of 10 paste to cause the wrapper at the head end of the bunch to closely adhere thereto. The discharge end of the port 419 is located at a point over which the rear end of the wrapper passes, so that the paste is applied to the 15 proper part of the wrapper.

When the wrapper has been completely wound upon the bunch, the gripper 421 and the cutter 423 are elevated through the action of the cam groove 431 on the stud or 20 projection 463 which is connected through the lever 462 and the rod 461 with the slide 445. The jaws by which the rolls 190 are carried at the same time begin to separate through the action of the cam groove 362 25 on the stud or projection 361 of the arm 369 on the sleeve 356 by which two of said jaws are carried, and the action of the cam groove 359 on the stud or projection 358 of the arm 357 on the shaft 355 by which the other two 30 of said jaws are carried. As 359 as said rolls being separated, the slide carries the gripper upward and the gripper closes on the cigar, the rotating polishing cup 432 is moved inwardly through the action of the 35 serrated flange 438 on the end of the shaft 434, to which said cup is connected, causing the cup intermittently to approach and recede from the tip end of the head of the cigar, and, rotating in the same direction in 40 which the wrapper was applied thereto, to polish and burnish the tip of the cigar and make all of the cigars of uniform size and shape at the tip. During this time the bunch on which the wrapper has been applied is supported by the tucking needle 192 and the gripper 431. As the slide 445 continues its upward movement, however, the tucking needle is automatically withdrawn from the tuck end of the cigar 45 and the cutter 423 is automatically actuated to cut the cigar at the tuck end. The jaws of the cutter 423 and the gripper 431, by which the completed cigar is held, now open and the cutter and gripper

per recede, finally disengaging the cigar and 65 allowing the same to fall down into any suitable receptacle which may be provided for it.

In order to brand each cigar after the wrapper has been applied, I secure in one 70 of the jaws of the gripper 431, the type 468, which project inwardly beyond the face of said jaw so that when the gripper is closed upon the completed cigar, the letters on the faces of said type will be impressed 75 thereon.

It will be seen from the foregoing that I have provided a machine in which all the operations necessary for the manufacture of a cigar are automatically performed, including the shaping of the filler tobacco, the delivery of the same onto the bunch-making mechanism, the feeding of the binder to the filler, the rolling of the binder around the filler to make the bunch, the shaping and compressing of the bunch while thus being rolled, the delivery of the bunch from the bunch-making mechanism to a bunch conveyer, the heating and compressing of the bunch while in said conveyer, the automatic 90 opening and closing of two of the lids of the receptacles which go to make up the bunch conveyer, the removal of the bunch from one of the open cups of receptacles, the introduction of a bunch from the bunch-making 95 mechanism into the other open receptacle, the delivery of the bunch removed from said conveyer to the wrapper-applying rolls, which have previously been opened, the automatic closing of said rolls and rotation 100 of the bunch within them, the cutting of the wrapper, the delivery of the same in flattened condition from the cutting die to the wrapper carrier, the raising of the wrapper carrier to receive the wrapper, the delivery 105 of the wrapper over a stretching roll or device rotating in a direction opposite the feed of the wrapper to the wrapper-applying rolls, the forcing of the wrapper down upon the bunch within said rolls by a tucking 110 needle and retaining the wrapper in place upon the bunch until more than one complete revolution of the latter has been made, the feeding of the wrapper at a variable speed to the bunch, the varying of the angle 115 at which the wrapper carrier lies to the bunch during the movement thereof longitudinally of said bunch, the cutting of the rear end of the wrapper as it reaches the head end of the bunch so that it will exactly fit said head when wound thereon, the application of paste to the wrapper as it is applied to the head of the bunch, the polishing of the tip of the bunch and the clipping of the tuck end thereof.

All the parts which go to make up the mechanisms described are operated from a single source of power and move in proper

sequence with each other so as to perform at just the right time all the functions for which they are designed.

The stopping and starting of the machine, 5 as a whole, is under the control of the operator, and the only hand operations necessary to be performed are the placing of the filler tobacco within the shaping receptacle designed therefor, the placing of the binder 10 upon the binder carrier, and the placing of the wrapper upon the cutting die.

The invention has been shown and described in the form which is deemed by me at this time to be the preferable one, but it 15 will be obvious that many changes may be made in the construction and arrangement of the parts which go to make up the complete machine. For example, instead of applying heat to the bunches while held under 20 compression in the cups or receptacles for the purpose of drying and setting said bunches in the desired form, I may dry said bunches while under compression in any other desired way. I do not, therefore, desire 25 to be limited to any of the specific details of construction, except as defined in the appended claims.

Having now described the invention, what I claim as new and desire to secure by Letters Patent, is:

1. In a cigar-machine, the combination of bunch-making mechanism, wrapper-applying mechanism, means for directly conveying bunches individually from the bunch-making 35 to the wrapping mechanism, and swinging wrapper carrying means for supplying cigar-wrappers to the wrapper applying mechanism.

2. In a cigar-machine, the combination of bunch-making mechanism, wrapper-applying mechanism, means for shaping the bunches, means for directly delivering bunches individually to the wrapper-applying 45 mechanism, and swinging means for supplying cigar-wrappers to the wrapper applying mechanism.

3. In a cigar-machine, the combination of bunch-making mechanism, bunch conveying and shaping mechanism, means for transferring bunches from the bunch-making to the conveying and shaping mechanism, bunch wrapping mechanism, means for transferring bunches from the conveying and shaping mechanism to the wrapping mechanism, and means for finishing the wrapped bunch while the latter is held by the wrapping mechanism.

4. In a cigar-machine, the combination of an oscillatory bunch-making mechanism, of a bunch conveyer and shaper into which the bunches are delivered from said mechanism, bunch-wrapping mechanism, a bunch-transferrer for removing bunches from said conveyer and shaper and delivering them to the wrapping mechanism, and means for

finishing the wrapped bunch while the latter is held by the wrapping-mechanism.

5. In a cigar machine, the combination of bunch-making mechanism, wrapper-applying mechanism, means for automatically delivering the bunches from the bunch-making to the wrapper-applying mechanism, means for maintaining the bunches under compression while passing from the bunch-making mechanism, and means for simultaneously subjecting the same to the action of heat.

6. In a cigar-machine, the combination of bunch-making mechanism, a bunch conveyer and shaper into which the bunches from said mechanism are delivered, means for maintaining the bunches under compression in said conveyer and shaper, means for simultaneously subjecting the same to the action of heat, wrapper-applying mechanism, and means for automatically removing the bunches from said conveyer and shaper and delivering the same to said wrapper-applying mechanism.

7. In a cigar machine, the combination of oscillatory bunch-making mechanism, and a cluster of wrapper-applying rolls, means for automatically opening and closing said rolls, conveying and shaping mechanism for receiving the bunches from the bunch-making mechanism, means for automatically transferring the bunches from the conveying and shaping mechanism into said rolls while the latter are in their open position, and means for feeding the wrapper to the bunch within said rolls.

8. In a cigar machine, the combination of oscillatory bunch-making mechanism and a cluster of wrapper-applying rolls, means for automatically opening and closing said rolls, conveying and shaping mechanism for receiving the bunches from the bunch-making mechanism, means for automatically transferring the bunches from the conveying and shaping mechanism into said rolls while the latter are in their open position, a wrapper-carrier for delivering a wrapper to the bunch within the rolls, means for imparting to the carrier a variable speed of movement toward said rolls, means for imparting to the carrier a movement in the direction of the length of the rolls, and means for simultaneously varying the angle at which said carrier lies to the rolls.

9. In a cigar machine, the combination of oscillatory bunch-making mechanism and a cluster of wrapper-applying rolls, means for automatically opening and closing said rolls, conveying and shaping mechanism for receiving the bunches from the bunch-making mechanism, means for automatically transferring the bunches from the conveying and shaping mechanism into the rolls while the latter are in their open position, a wrapper carrier for delivering a wrapper

to the bunch within said rolls, and means for automatically cutting a wrapper to the proper shape and transferring the same into proper position upon the carrier.

16. In a cigar machine, the combination of oscillatory bunch-making mechanism and a cluster of wrapper-applying rolls, means for automatically opening and closing said rolls, conveying and shaping mechanism for receiving the bunches from the bunch-making mechanism, means for automatically transferring the bunches from the conveying and shaping mechanism into the rolls while the latter are in their open position, means for feeding a wrapper to the bunch within the rolls, and means for simultaneously imparting a tension upon and friction to said wrapper as it is delivered to the bunch for stretching the same and removing the creases and wrinkles therefrom.

17. In a cigar machine, the combination of oscillatory bunch-making mechanism, wrapper-applying mechanism, mechanism for receiving the bunch and delivering the latter to the wrapper-applying mechanism, and means for maintaining the bunch under compression while passing from the bunch making mechanism to the receiving mechanism.

18. In a cigar machine, the combination of oscillatory bunch-making mechanism, a traveling bunch conveyor into which the bunches from said mechanism are delivered, means for maintaining the bunches under compression in said conveyor, wrapper-applying mechanism, and means for lifting the bunches from said conveyor and transferring the same to said wrapper-applying mechanism.

19. In a cigar machine, the combination of oscillatory bunch-making mechanism, an endless bunch conveyor having a step by step movement into which the bunches from said mechanism are delivered, means for maintaining the bunches under compression in said conveyor, wrapper-applying mechanism, and means for removing the bunches from said conveyor and transferring the same to said wrapper-applying mechanism.

20. In a cigar machine, the combination of oscillatory bunch-making mechanism, an endless bunch conveyor into which the bunches from said mechanism are delivered, means for maintaining the bunches under compression in said conveyor, wrapper-applying mechanism, and oscillatory means for removing the bunches from said conveyor and transferring the same to said wrapper-applying mechanism, the said oscillatory means being located between the wrapper-applying mechanism and the conveyor.

21. In a cigar machine, the combination of bunch-making mechanism, an endless

bunch conveyor into which the bunches from said mechanism are delivered, means for maintaining the bunches under compression in said conveyor, wrapper-applying mechanism, and oscillatory means, a lifting device for lifting said bunches from the said conveyor and transferring the same to the wrapper-applying mechanism.

22. In a cigar machine, means for lifting the head end of the bunch as it is being delivered to said means, and the head of the bunch, if desired, will approximately fit over said head when completely wound theron, additional means for cutting or snipping the wrapper at the tip of the bunch to obviate the formation of any projecting portion of said bunch when wound, thereby to wind around the body of the bunch, and means for applying paste to the bunch portion.

23. In a cigar machine, means for cutting the head end of the bunch, or to be held delivered to said means, upon the tip of the bunch by the said means, so as to prevent the bunch from being wound around the body of the bunch, and means for applying paste to the bunch portion of the bunch, while the bunch is being wound, so as to obviate the formation of any projecting portion of the bunch when wound around the body of the bunch at the tip portion.

24. In a cigar machine, the combination with a bunch conveyor and compression, applying mechanism, of an endless bunch transferred compression conveyor, a bunch traveling mechanism, and a bunch compression means for maintaining the bunches under compression in said conveyor to maintain the tip position of the bunch.

25. In a cigar machine, the combination with a bunch supporting means and wrapping mechanism, of an oscillatory bunch transmitter, a supporting a pair of arms, the said arms being hinged to a carrier, and a pair of arms and means for moving said carrier toward and away from each other so as to hold said carrier to maintain the proper ends of the bunch.

26. In a cigar machine, the combination with a bunch conveyor and wrapping mechanism, of a bunch transmitter comprising a pair of arms, parallel extending means carried on said arms, means for shifting the position of said position on said arms, and means for moving said arms, toward and away from each other so as to hold said carrier to maintain the proper ends of the bunch.

27. In a cigar machine, the combination with a raising mechanism, and a bunch conveyor having its opposite ends open, of a bunch transmitter movable toward and away from said conveyor, forwardly extending needles on said transmitter adapted to inci-

- pass the opposite ends of said receptacle, and means automatically thrown into operation for moving said needles into the open ends of said receptacle to cause the same to 5 puncture and engage the opposite ends of the bunch therein.
22. In a cigar machine, the combination with wrapping mechanism and a bunch receptacle having its opposite ends open, of a 10 bunch transferrer movable toward and away from said receptacle, the same comprising a pair of arms adapted to pass by the ends of said receptacle, inwardly extending needles on said arms, and means 15 automatically thrown into operation after said transferrer approaches said receptacle for moving said arms toward each other and thereby causing said needles to enter the open ends of said receptacle and to puncture the opposite ends of the bunch therein.
23. In a cigar machine, the combination with wrapping mechanism and a bunch receptacle having its opposite ends open, of a bunch transferrer movable toward and 25 away from said receptacle, the same comprising a pair of arms adapted to pass by the ends of said receptacle, inwardly extending needles carried by said arms, means for adjusting the position of said needles in said 30 arms, and means automatically thrown into operation after said transferrer approaches said receptacle for moving said arms toward each other and thereby causing said needles to enter the open ends of said 35 receptacle and to puncture the opposite ends of the bunch therein.
24. In a cigar machine, the combination with a bunch support having open ends and wrapping mechanism, of a bunch transferrer 40 comprising a shaft, a pair of arms capable of movement on said shaft in the direction of its length, bunch-engaging means on said arms to enter the open ends of said bunch support, and means for automatically moving said arms on said shaft toward and away from each other to cause the engaging means thereon to be moved into and out of operative relation to the bunch.
25. In a cigar machine, a bunch support 50 through which the ends of the bunch are adapted to project, a fulcrumed oscillatory bunch transferrer having bunch-cutting means thereon to trim the bunch while the latter is in the support prior to the transfer of the same, and wrapping mechanism to which the bunch is delivered.
26. In a cigar machine, a bunch support 55 through which the ends of the bunch are adapted to project, a fulcrumed oscillatory bunch transferrer provided with means for clipping the ends of the bunch to trim the bunch while the latter is in the support prior to the transfer of the same, and wrapping mechanism to which the bunch is delivered.
27. In a cigar machine, a bunch support 60
- through which the ends of the bunch are adapted to project, a fulcrumed oscillatory bunch transferrer having bunch-engaging means thereon and means for clipping the ends of the bunch to trim the bunch while the latter is in the support prior to the transfer of the same, and wrapping mechanism to which the bunch is delivered.
28. In a cigar machine, the combination of wrapping mechanism, a bunch transferrer having bunch-engaging means thereon, cutters for clipping the ends of the bunch, and means for automatically throwing the bunch-engaging means into operation after the ends of the bunch have been 70 cut.
29. In a cigar machine, the combination with wrapping mechanism, of a bunch receptacle having its opposite ends open, and a bunch transferrer having bunch engaging 75 means and cutting blades thereon movable opposite the open ends of said receptacle for clipping the projecting ends of the bunch therein.
30. In a cigar machine, the combination with wrapping mechanism, of a bunch transferrer having cutting blades for the ends of the bunch mounted thereon, and longitudinally movable bunch-engaging members extending through openings in said blades. 80
31. In a cigar machine, the combination with wrapping mechanism, of a bunch transferrer comprising a pair of cutting blades for the ends of the bunch, bunch-engaging needles projecting through openings in said 85 blades, and means for automatically moving said needles toward each other after said blades have acted upon said bunch to clip it.
32. In a cigar machine, the combination with wrapper applying mechanism and means for transferring a wrapper thereto, of a vertically reciprocating carrier provided with means for feeding a wrapper therefrom to the bunch. 90
33. In a cigar machine, the combination with wrapper applying mechanism and means for transferring a wrapper thereto, of a vertically reciprocating wrapper carrier provided with means for feeding a wrapper to the said mechanism, and means 95 for varying the feed of the wrapper in accordance with the different diameters of the bunch.
34. In a cigar machine, the combination with wrapper applying mechanism and means for transferring a wrapper thereto, of a vertically reciprocating wrapper carrier, and means thereon for feeding a wrapper and means for varying its angular disposition with relation to said mechanism to 100 effect proper application of the wrapper to the bunch.
35. In a cigar machine, the combination with wrapper applying mechanism and means for transferring a wrapper thereto, 105

- of a vertically reciprocatory carrier, a wrapper-supporting device thereon adapted to travel at variable rates of speed between the angles of presentation of the wrapper 5 to effect the proper feeding thereof.
36. In a cigar machine, the combination with wrapper applying mechanism and means for transferring a wrapper thereto, of a vertically reciprocatory carrier including suction mechanism, and a movable element thereon adapted to support a wrapper under suction and to feed the wrapper to the bunch.
37. In a cigar machine, the combination 15 with wrapper applying mechanism and means for transferring a wrapper thereto, of a vertically-reciprocatory carrier, a wrapper-feeding device thereon adapted to support a wrapper, and means for imparting variable rates of speed of travel to the carrier while feeding the wrapper to the bunch.
38. In a cigar machine, the combination 25 with wrapper applying mechanism and means for transferring a wrapper thereto, of a vertically-reciprocatory wrapper-carrier, a suction box, and a wrapper-feeding device movable thereover and adapted to present a wrapper to the wrapper-applying 30 mechanism at variable rates of speed and variable angles.
39. In a cigar machine, the combination 35 with wrapper applying mechanism and means for transferring a wrapper thereto, of a vertically-reciprocatory wrapper carrier including a suction box, a wrapper-feeding device disposed thereon, and means for imparting variable reciprocatory movements to said device.
40. In a cigar machine, the combination 45 with wrapper applying mechanism and means for transferring a wrapper thereto, of a vertically-reciprocatory wrapper carrier including a suction box, a combined wrapper supporting and wrapper feeding device movable thereon, means for imparting reciprocatory movement to the device, and means to impart variable rates of movement to the carrier.
50. 41. In a cigar machine, the combination 55 with wrapper applying mechanism and means for transferring a wrapper thereto, of a vertically-reciprocatory wrapper carrier movable to and fro in an arc in a horizontal plane and including suction mechanism, a wrapper-feeding device movable thereover, and means for imparting reciprocatory movements thereto.
42. In a cigar machine, the combination 60 with wrapper applying mechanism and means for transferring a wrapper thereto, of a vertically-reciprocatory carrier movable to and fro in an arc in a horizontal plane, a wrapper-feeding device movable 65 thereover, and means for automatically varying the rates of speed of horizontal movement of the carrier.
43. In a cigar machine, the combination with wrapper applying mechanism and means for transferring a wrapper thereto, 70 of a vertically-reciprocatory carrier having a to and fro arcuate movement in a horizontal plane, a wrapper feeding device movable thereover, suction means coacting with the feeding device, and means for varying the 75 speed of movement of the wrapper-feeding device.
44. In a cigar machine, a cluster of wrapper-applying rolls, a wrapper-carrier having a wrapper-feeding device thereon, 80 means for delivering a wrapper to a bunch within said rolls, and means for raising and lowering the carrier and wrapper-feeding device.
45. In a cigar machine, a cluster of 85 wrapper-applying rolls, a wrapper carrier for delivering a wrapper to the bunch within said rolls, a wrapper support on the side of said rolls opposite said carrier, and means for automatically raising said carrier to a point above said rolls, to deliver the projecting end of the wrapper onto the said support, and for returning said carrier to its normal depressed position.
46. In a cigar machine, a cluster of 90 wrapper-applying rolls, a wrapper carrier for delivering a wrapper to the bunch within said rolls, a stationary suction-plate on the side of said rolls opposite said carrier, and means for automatically raising said carrier to a point above said rolls to deliver 95 the projecting end of the wrapper upon said plate and for automatically returning said carrier to its normal depressed position.
47. In a cigar machine, a cluster of 100 wrapper-applying rolls, a wrapper carrier for delivering a wrapper to the bunch within said rolls, means for raising said carrier to a point above said rolls and for returning 105 the same to its normal depressed position, and a wrapper-transferring roller movable over said carrier when the latter is in its raised position to deposit a wrapper thereon.
48. In a cigar machine, a cluster of 110 wrapper-applying rolls, a wrapper carrier for delivering a wrapper to the bunch within said rolls, the same comprising a suction-box having openings in its upper wall and a perforated apron traveling thereover, 115 means for raising said carrier to a point where its upper wall is above said rolls and for returning the same to its normal depressed position, a die, means for applying suction to the interior thereof, a perforated 120 roller coöperating with said die for cutting the tobacco leaf thereon into proper shape for a wrapper, means for applying suction to the inside of said roller, means for revolving said roller over said die and over 125 130

5. said carrier when the latter is in its raised position, means for automatically increasing the suction in said roller as it passes over said die to enable the same to lift the cut wrapper therefrom, and means for decreasing the suction in said roller as it passes over said carrier whereby the wrapper on said roller is delivered upon said carrier.
10. 49. In a cigar machine, a carrier for delivering a wrapper to the bunch and means for automatically varying the angle between the carrier and the bunch to compensate for variations in the shape of the bunch to which the wrapper is applied.
15. 50. In a cigar machine, a wrapper carrier for delivering a wrapper to the bunch, means for moving said carrier longitudinally of the bunch, the said wrapper carrier having a vertically reciprocatory movement during the delivery of the wrapper therefrom, and means for simultaneously varying the angle between said carrier and the bunch to compensate for variations in the shape of the bunch to which the wrapper is applied.
20. 51. In a cigar machine, a vertically reciprocatory wrapper carrier for delivering a wrapper to the bunch, means for automatically moving said carrier longitudinally of the bunch at a variable speed, the said wrapper carrier having a vertically reciprocatory movement during the delivery of the wrapper therefrom, and means for simultaneously varying the angle between said carrier and the bunch to compensate for variations in the shape of the bunch to which the wrapper is applied.
25. 52. In a cigar machine, a vertically reciprocatory wrapper carrier for delivering a wrapper to a bunch, means cooperating with the carrier for feeding the wrapper at a variable speed to the bunch, and means for simultaneously moving said carrier at a variable speed longitudinally of the bunch.
30. 53. In a cigar machine, a vertically reciprocatory wrapper carrier for delivering a wrapper to a bunch, means cooperating with the carrier for feeding the wrapper at a variable speed to the bunch, means for moving said carrier at a variable speed longitudinally of the bunch, and means for simultaneously varying the angle between said carrier and the bunch to compensate for variations in the shape of the bunch to which the wrapper is applied.
35. 54. In a cigar machine, a vertically reciprocatory wrapper carrier for delivering a wrapper to a bunch, means thereon for automatically feeding the wrapper at a variable speed toward the bunch, means for automatically moving said carrier at a variable speed longitudinally of the bunch, and means for automatically varying the angle between said carrier and the bunch to compensate for variations in the shape of the bunch to which the wrapper is applied.
40. 55. In a cigar machine, a cluster of wrapper-applying rolls, a wrapper carrier, means thereon for delivering a wrapper at variable speed to the bunch within said rolls, means for raising and lowering said carrier, means for moving the same longitudinally of the bunch, and means for simultaneously varying the angle between said carrier and the bunch to compensate for variations in the shape of the bunch to which the wrapper is applied.
45. 56. In a cigar machine, a cluster of wrapper-applying rolls and a vertically reciprocatory wrapper carrier including suction means for delivering a wrapper to the bunch within said rolls, the same comprising a frame and an apron thereon movable toward said rolls, means for moving said frame bodily longitudinally of said rolls, and means for simultaneously swinging the same on its pivot.
50. 57. In a cigar machine, a cluster of wrapper-applying rolls and a vertically reciprocatory wrapper carrier including suction means for delivering a wrapper to the bunch within said rolls, the same comprising a frame and an apron thereon movable toward said rolls, means for imparting a variable speed of movement to said apron, means for moving said frame bodily longitudinally of said rolls, and means for simultaneously swinging the same on its pivot.
55. 58. In a cigar machine, a cluster of wrapper-applying rolls and a vertically reciprocatory wrapper carrier including suction means for delivering a wrapper to the bunch within said rolls, the same comprising a frame and an apron thereon movable toward said rolls, means for imparting a variable speed of movement to said apron toward said rolls, means for moving said carrier bodily at a variable speed longitudinally of said rolls, and means for swinging said frame on its pivot.
60. 59. In a cigar machine, a cluster of wrapper-applying rolls and a vertically reciprocatory wrapper carrier including suction means movable longitudinally of said rolls, the same comprising a frame, an apron movable over the same for delivering a wrapper to the bunch within said rolls, a pair of rollers to which the opposite ends of said apron are attached, and means for imparting a variable speed of rotation to said rollers.
65. 60. In a cigar machine, a cluster of wrapper-applying rolls and a wrapper carrier including suction means movable longitudinally of said rolls, the same comprising a frame, an apron movable over the same for delivering a wrapper to the bunch within said rolls, a pair of rollers to which the

- opposite ends of said apron are attached, a cam, and connections between said cam and one of said rollers for imparting a variable speed of movement thereto.
61. In a cigar machine, a cluster of wrapper-applying rolls and a wrapper carrier including suction means movable longitudinally of said rolls, the same comprising a frame, an apron movable over the same for delivering a wrapper to the bunch within said rolls, a pair of intergeared rollers to which the opposite ends of said apron are attached, a pinion connected to one of said rollers, a rotary shaft having a disk thereon provided with a cam groove, a rocking lever having a stud or projection thereon fitting within said groove and gearing, providing for universal movement, between said rocking lever and said pinion.
62. In a cigar machine, a cluster of wrapper-applying rolls and a wrapper carrier including suction means movable longitudinally of said rolls, the same comprising a frame, an apron movable over the same for delivering a wrapper to the bunch within said rolls, a pair of intergeared rollers to which the opposite ends of said apron are attached, a pinion connected to one of said rollers, a shaft mounted in bearings in a bracket on said frame and having a pinion thereon meshing with the pinion on said roller, a rotary disk having a cam groove therein, a rocking lever having a stud or projection thereon fitting within said groove, a segmental rack or gear on said lever, a pinion meshing with said rack or gear, and secured to a shaft mounted in fixed bearings, and a universal extensible coupling between the latter shaft and the shaft carrying the pinion which meshes with the pinion on said roller.
63. In a cigar machine, a cluster of wrapper-applying rolls and a vertically reciprocating wrapper carrier including suction means movable longitudinally of said rolls, and including an apron upon which the wrapper is supported, and a cam for imparting a variable speed of movement to said apron for delivering the wrapper at a variable speed to the bunch within said rolls.
64. In a cigar machine, a cluster of wrapper-applying rolls, a wrapper carrier for delivering the wrapper to the bunch within said rolls, the same being movable longitudinally thereof and comprising a frame having a suction box therein, provided with openings in its upper wall, a perforated apron movable longitudinally over said suction box toward and from said rolls, a guide roller at one end of said box around which said apron passes, and a suction plate located adjacent to said roller at the delivery end of said carrier.
65. In a cigar machine, a wrapper carrier for delivering a wrapper to a bunch, comprising a frame having a suction-box therein provided with openings in its upper wall, a perforated apron movable over said suction-box, a chamber within said frame for connection with a suction pipe, said chamber communicating with said suction-box, and a passage for said apron between said chamber and said suction box, but cut off from connection with both.
66. In a cigar machine, a wrapper carrier for delivering a wrapper to a bunch, comprising a frame having a suction-box therein provided with openings in its upper wall, a perforated apron movable over said suction-box, a roller at one end of said suction box around which said apron passes, a suction-plate at the delivery end of said carrier, adjacent to said roller, a chamber beneath said suction-box having means thereon for the attachment of a suction-pipe, a passage for the apron located between said suction-box and said chamber but cut off from both, passages leading from said chamber around said apron passage to said suction-box, and connections between the latter passages and said suction-plate.
67. In a cigar machine, the combination with wrapper transferring and wrapper applying mechanisms, of a pivotally mounted vertically reciprocating wrapper carrier for delivering a wrapper to a bunch, having a pinion thereon concentric with its pivot, a gear meshing with said pinion, means for rapidly moving said carrier longitudinally, of the bunch, and means for simultaneously rotating said gear to cause a swinging movement on its pivot to be automatically imparted to said carrier.
68. In a cigar machine, a pivotally mounted wrapper carrier for delivering a wrap- 105 per to a bunch having a pinion thereon concentric with its pivot, a gear meshing with said pinion, an eccentric projection on said gear, means for moving said carrier and gear longitudinally of the bunch, and a cam 110 operating upon said eccentric projection for automatically rotating said gear and swinging said carrier on its pivot.
69. In a cigar machine, a pivotally mounted wrapper carrier for delivering a wrap- 115 per to a bunch, having a pinion thereon concentric with its pivot, a gear meshing with said pinion, an eccentric stud or projection on said gear, means for moving said carrier longitudinally of the bunch, and a cam 120 groove in a relatively fixed part within which said stud or projection moves for rotating said gear and swinging said carrier on its pivot.
70. In a cigar machine, a pivotally mounted wrapper carrier for delivering a wrapper to a bunch, a pinion on said carrier concentric with its pivot, a slide on which said carrier is pivoted, a support on which said slide is mounted, a gear mounted in said 125 130

- slide and meshing with said pinion, a cam groove in said support, an eccentric stud or projection on said gear fitting within said groove, and means for moving said slide longitudinally of the bunch.
71. In a cigar machine, a cluster of wrapper-applying rolls, a slide movable longitudinally of said rolls, a support on which said slide is mounted having an irregularly shaped cam groove therein, a wrapper carrier for delivering a wrapper to the bunch within said rolls pivoted to said slide and having a pinion thereon concentric with its pivot, a gear mounted on said slide and meshing with said pinion, an eccentric stud or projection on said gear fitting within said cam groove, and means for imparting a variable speed of movement to said slide.
72. In a cigar machine, a cluster of wrapper-applying rolls, a slide movable longitudinally thereof having a segmental slot therein and provided with two intersecting recesses, a support on which said slide is mounted having an irregularly shaped cam groove therein, a wrapper carrier for delivering a wrapper to the bunch within said rolls, the said carrier being pivoted to said slide and having a pinion thereon concentric with its pivot which fits within one of said intersecting recesses, a gear wheel fitting within the other of said intersecting recesses and meshing with said pinion, and an eccentric stud or projection on said gear extending through the segmental slot in said slide and projecting into said cam groove.
73. In a cigar machine, a cluster of wrapper-applying rolls, a slide movable longitudinally thereof, a support on which said slide is mounted having an irregularly shaped cam groove therein whose opposite ends are connected by a straight groove, switches at the points of intersection of said grooves, a wrapper carrier for delivering a wrapper to the bunch within said rolls, the same being pivoted to said slide and having a pinion thereon concentric with its pivot, a gear on said slide meshing with said pinion, and an eccentric stud or projection on said gear fitting and adapted to move within the groove in said support.
74. In a cigar machine, a vertically reciprocating carrier including suction mechanism, a wrapper feeding device thereon adapted to support a wrapper, a cluster of rolls one of which is cigar shaped, means for inserting the end of a wrapper on said carrier adjacent to the latter roll when the carrier is in raised position, and means for depressing said carrier with wrapper thereon to which suction has been applied for the purpose of making the wrapper travel taut over the cigar-shaped roll.
75. In a cigar machine, the combination with wrapper applying mechanism, of a vertically reciprocating carrier, and means
- held by the carrier for mechanically feeding and delivering a wrapper to the bunch while said wrapper is under suction and while it is being wrapped around a bunch.
76. In a cigar machine, a vertically reciprocating carrier, a wrapper feeding device thereon adapted to support a wrapper, a cluster of rolls, one of which is cigar-shaped, means for inserting the end of a wrapper on said carrier adjacent to the latter roll when the carrier is in raised position, suction mechanism cooperating with said wrapper feeding device, and means for depressing the carrier with the wrapper thereon while under suction so as to create an extra tautness to the wrapper between the said cigar-shaped roll and the bunch around which the wrapper is being applied.
77. In a cigar machine, the combination with wrapper applying mechanism, of a carrier, and means held by the carrier for simultaneously feeding a wrapper to a bunch at variable rates of speeds and angles in proportion to the amount of wrapper being taken up by the bunch between the various angles of presentation while the wrapper is traveling and being fed to the bunch, the carrier being moved in unison with the wrapper at variable rates of speed between the angles of presentation and at various angles during this operation.
78. In a cigar machine, the combination with wrapper applying mechanism, of a carrier, a wrapper feeding device movable on the carrier under suction and adapted to support a wrapper, and means for simultaneously moving said wrapper carrier at variable rates of speed and at variable angles in conjunction with the wrapper feeding device.
79. In a cigar machine, the combination with wrapper applying mechanism, of a carrier, a wrapper feeding device thereon adapted to support a wrapper, means for simultaneously moving said carrier at variable rates of speed and varying angles in conjunction with the wrapper feeding device, thus to effect proper feeding of the wrapper, and means operating to stretch, remove the creases from the wrapper, and to bulge it at its various parts in conformity with the shape of the bunch being rolled.
80. In a cigar machine, a carrier, a movable wrapper feeding device thereon to which suction is applied and adapted to support a wrapper, a cluster of wrapper-applying rolls one of which is of the exact size of the bunch to be wrapped, means for depositing a bunch within the rolls, a tucking needle, means for applying paste at the tip portion of the cigar, and means for applying suction to the free end of the wrapper.
81. In a cigar machine, a vertically reciprocating wrapper carrier, a traveling

- wrapper feeding device thereon adapted to support a wrapper, a cluster of wrapper-applying rolls, one of which is cigar-shaped, a tucking needle, means for operating the needle for tucking the wrapper at the tuck end of the bunch, and means for immediately depressing the wrapper carrier, thereby causing the wrapper to pass over and in frictional contact with the cigar-shaped roll, 5 which revolves in an opposite direction to that from which the wrapper is being fed, thereby increasing the tautness of the wrapper between the roll and the bunch and decreasing the tautness between the roll and the carrier.
82. In a cigar machine, a vertically reciprocatory carrier, a wrapper feeding device thereon adapted to support a wrapper, wrapper-applying rolls one of which is cigar-shaped, means for tucking the wrapper at the tuck end of the bunch, and means for immediately depressing the carrier and the wrapper to cause the wrapper to pass over and in frictional contact with the 10 cigar-shaped roll which revolves in an opposite direction to that from which the wrapper is being fed to the bunch for the purpose of removing the creases in the wrapper.
83. In a cigar machine, two pairs of pivoted jaws adapted to be moved toward and away from each other, a cluster of wrapper-applying rolls carried by said jaws, the said cluster comprising five rolls, two of which 15 are mounted in the two jaws on one side, two more of which are mounted in the two jaws on the other side, and the remaining roll being disposed above the said two pairs, means for separating the remaining roll 20 from the others of the cluster when said jaws are moved away from each other, and means for automatically moving the latter roll back into its normal position to complete the cluster when said jaws are moved 25 toward each other.
84. In a cigar machine, two pairs of pivoted jaws, the members of each pair lying opposite each other and one member of one of the pairs being provided with a recess 30 in its upper end, a cluster of wrapper-applying rolls carried by said jaws, the said cluster comprising five rolls, two of which are mounted between the jaws on one side and two more of which are mounted between 35 the jaws on the opposite side, the remaining roll being longer than the others and having one end fitting when in its normal position down within said recess, means for elevating and separating the latter roll 40 from the remaining rolls of the cluster when said jaws are moved away from each other, and means for automatically depressing the latter roll and causing the same to assume its normal position within said recess when 45 said jaws are moved toward each other.

85. In a cigar machine, two pairs of pivoted jaws adapted to be moved toward and away from each other, a cluster of wrapper-applying rolls carried thereby, two spring arms in the free ends of which the opposite 50 ends of one of said rolls are mounted, the said spring arms being provided with two branches at their opposite ends, one of the branches of each of said arms being secured to one of said jaws and the other branch of each of said arms extending toward the adjacent jaw, and laterally extending arms on said adjacent jaws adapted to engage the free ends of said branches when said 55 jaws approach each other.

86. In a cigar machine, the combination with wrapper applying mechanism, of means for cutting the head end of the wrapper as it is being delivered to and wound upon the head end of the bunch, 60 additional means for nicking the wrapper at the tip of the bunch, and means for simultaneously applying paste to the wrapper as it is being delivered to and wound upon the head end of the bunch.

87. In a cigar machine, the combination with wrapper applying mechanism, of means for cutting the head end of the wrapper as it is being delivered to and wound upon the head end of the bunch, additional means for nicking the wrapper at the tip of the bunch, and means for automatically delivering and applying paste to the wrapper as it is being delivered to and wound upon the head end of the bunch.

88. In a cigar machine, the combination with wrapper applying mechanism, of means for cutting the head end of the wrapper as it is being delivered to and wound upon the head end of the bunch, additional means for nicking the wrapper at the tip of the bunch, and means for automatically delivering and applying paste to a portion of the exterior surface of the 100 wrapper as it is being delivered to and wound upon the head end of the bunch.

89. In a cigar machine, the combination with wrapper applying mechanism, of means for cutting the head end of the wrapper as it is being delivered to and wound upon the head end of the bunch, additional means for nicking the wrapper at the tip of the bunch, a reciprocator plunger for delivering paste to the wrapper as it is being delivered to and wound upon the head of the bunch, and means for automatically actuating said plunger.

90. In a cigar machine, the combination with wrapper applying mechanism, of means for cutting a tongue in the wrapper to 115 constitute the tip, and means for automatically nicking the tongue thus formed to permit of its proper application to the cigar.

91. In a cigar machine, the combination 120

with wrapper-applying mechanism, of a reciprocating blade for nicking the wrapper at the tip of the bunch while the same is disposed within the wrapper-applying mechanism, and means for automatically actuating said blade.

92. In a cigar machine, the combination with wrapper-applying mechanism, of means for cutting the head end of the wrapper as it is being delivered to and wound upon the head end of the bunch; additional means for nicking the wrapper at the tip of the bunch while the wrapper is being completely wound around the head of the bunch, and means for automatically actuating said cutting and nicking mechanisms.

93. In a cigar machine, a cluster of wrapper-applying rolls within which the bunch is rotated, two pairs of pivoted jaws by which said rolls are carried, a bracket, a cutter for the head end of the wrapper carried by said bracket and located at the head end of the bunch, a slide mounted on said bracket, a cutter secured to said slide cooperating with the first cutter, and means for reciprocating said slide to move said cutters into and out of coöperative relation with each other.

94. In a cigar machine, a cluster of wrapper-applying rolls within which the bunch is rotated, two pairs of pivoted jaws by which said rolls are carried, a bracket, a cutter for the head end of the wrapper carried by said bracket and located at the head end of the bunch, a slide mounted on said bracket, a cutter secured to said slide cooperating with the first cutter, a nicking cutter for the wrapper carried by said slide and movable opposite the tip end of the bunch, and means for automatically reciprocating said slide.

95. In a cigar machine, a cluster of wrapper-applying rolls within which the bunch is rotated, two pairs of pivoted jaws by which said rolls are carried, a bracket, a cutter for the head end of the wrapper carried by said bracket and located at the head end of the bunch, a slide mounted on said bracket, a cutter secured to said slide cooperating with the first cutter, a paste receptacle communicating with a cylindrical passage or tube in said bracket, a plunger carried by said slide and adapted to fit within said passage, and means for automatically reciprocating said slide.

96. In a cigar machine, wrapper-applying rolls, a suction device on one side of the rolls and constituting a wrapper support, means for delivering one end of a wrapper upon the support, and means for forcing the wrapper down within the rolls and into contact with the bunch.

97. In a cigar machine, wrapper applying rolls, a suction device on one side of the rolls and constituting a wrapper support, a wrap-

per carrier on the other side of the rolls to deliver the projecting end of the wrapper on to said support, and means to engage the wrapper while on the support and to force it down within the rolls into contact with the bunch.

98. In a cigar machine, wrapper-applying rolls, a suction device on one side of the rolls and constituting a wrapper support, means to deliver the projecting end of the wrapper onto the support, and a flexible tucking needle to force the same down within the rolls into contact with the bunch.

99. In a cigar machine, a cluster of wrapper-applying rolls within which the bunch is rotated, two pairs of pivoted jaws by which said rolls are carried, a bracket having a cylindrical passage extending therethrough and communicating with a paste supply pipe, a curved cutting blade carried by said bracket for severing the head end of the wrapper as it is being delivered and wound upon the bunch, a slide mounted for reciprocation on said bracket, a curved blade secured to said slide and coöperating with the curved blade on said bracket, a nicking cutter for the wrapper carried by said slide and movable opposite the tip end of the bunch within said rolls, a plunger carried by said slide and adapted to fit and move within said passage, and means for automatically reciprocating said slide.

100. In a cigar machine, a cluster of wrapper-applying rolls within which the bunch is rotated, two pairs of pivoted jaws by which said rolls are carried, a bracket mounted for rocking movement transversely of said cluster of rolls at the head end thereof, a cutter for the head end of the wrapper carried by said bracket, a slide on said bracket, a cutter secured to said slide cooperating with the first cutter, means for reciprocating said slide to move the cutter thereon into and out of coöperative relation with the other cutter, means for automatically swinging said jaws on their pivots to open and close said cluster of rolls, and means for simultaneously rocking said bracket.

101. In a cigar machine, a cluster of wrapper-applying rolls within which the bunch is rotated, two pairs of jaws by which said rolls are carried, a rock shaft to which two of said jaws are secured, a sleeve loosely mounted on said shaft to which the other jaws are secured, a bracket mounted for rocking movement transversely of said cluster of rolls at the head end thereof, a cutter for the head end of the wrapper carried by said bracket, a slide mounted on said bracket, a cutter secured to said slide cooperating with the first cutter, means for reciprocating said slide to move the cutter thereon into and out of coöperative relation with the other cutter, means for automati-

callly rocking said shaft and said sleeve in opposite directions to swing said jaws to open and close the cluster of rolls carried thereby, and operative connections between 5 said shaft and said bracket whereby said bracket is rocked upon its support when said jaws are opened and closed.

102. In a cigar machine, a cluster of wrapper-applying rolls within which the bunch is rotated, two pairs of jaws by which said rolls are carried, a rock shaft to which two of said jaws are secured, a sleeve loosely mounted on said shaft to which the other jaws are secured, a bracket mounted for 15 rocking movement transversely of said cluster of rolls at the head end thereof, a cutter for the head end of the wrapper carried by said bracket, a slide mounted on said bracket, a cutter secured to said slide for 20 operating with the first cutter, means for reciprocating said slide to move the cutter thereon into and out of cooperative relation with the other cutter, a crank arm on said bracket, a crank arm on said shaft, a link 25 connecting said crank arms, and means for automatically rocking said shaft and said sleeve in opposite directions to swing said jaws to open and close the cluster of rolls carried thereby, and connections between 30 said shaft and said bracket serving to rock said bracket in accordance with the movement of said shaft.

103. In a cigar machine, a cluster of wrapper-applying rolls within which the bunch is rotated, two pairs of pivoted jaws by which said rolls are carried, a bracket mounted for rocking movement transversely of said cluster of rolls at the head end thereof, the said bracket having a cylindrical passage 45 therein, a paste receptacle communicating with said passage, a cutter for the head end of the wrapper carried by said bracket, a slide on said bracket, a cutter secured to said slide operating with the first cutter, a plunger also carried by said slide and adapted to fit within said passage, means for reciprocating said slide to move the cutter thereon into and out of cooperative relation with the other cutter and 50 to move said plunger back and forth in said passage, means for automatically swinging said jaws on their pivots to open and close said cluster of rolls, and means for simultaneously rocking said bracket.

104. In a cigar machine, a cluster of wrapper-applying rolls within which the bunch is rotated, two pairs of jaws by which said rolls are carried, one of said jaws being provided with a rock communicating with the head end of the cigar in said rolls, a rock shaft to which two of said jaws are secured, a sleeve loosely mounted on said shaft to which the other jaws are secured, a bracket mounted for rocking movement 55 transversely of said cluster of rolls at the head end of the cigar in said rolls, a cutter for the head end of the cigar in said rolls, a slide on said bracket, a cutter secured to said slide operating with the first cutter, a plunger also carried by said slide and having a cylindrical passage therethrough, a paste receptacle communicating with said passage, a crank arm on said shaft having a link 60 connecting with the crank arm on said bracket, a cutter for the head end of the wrapper carried by said bracket, and means for reciprocating said slide to move the cutter thereon into and out of cooperative relation with the other cutter, and means for automatically swinging said jaws on their pivots to open and close the cluster of rolls carried thereby, and for simultaneously rocking said bracket.

105. In a cigar machine, a cluster of wrapper-applying rolls within which the bunch is rotated, two pairs of jaws by which said rolls are carried, a rock shaft to which two of said jaws are secured, a sleeve loosely mounted on said shaft to which the other jaws are secured, a bracket mounted for rocking movement transversely of said cluster of rolls at the head end of the cigar in said rolls, a cutter for the head end of the wrapper carried by said bracket, a slide on said bracket, a cutter secured to said slide for operating with the first cutter, a plunger also carried by said slide and having a cylindrical passage therethrough, a paste receptacle communicating with said passage, a crank arm on said shaft having a link connecting with the crank arm on said bracket, a cutter for the head end of the wrapper carried by said bracket, and means for reciprocating said slide to move the cutter thereon into and out of cooperative relation with the other cutter, and means for automatically swinging said jaws on their pivots to open and close the cluster of rolls carried thereby, and for simultaneously rocking said bracket.

106. In a cigar machine, a cluster of wrapper-applying rolls within which the bunch is rotated, two pairs of jaws by which said rolls are carried, a rock shaft to which two of said jaws are secured, a sleeve loosely mounted on said shaft to which the other jaws are secured, a bracket mounted for rocking movement transversely of said cluster of rolls at the head end thereof, the said bracket being provided with a crank arm, and a bearing sleeve and having a cylindrical passage therethrough, a paste receptacle communicating with said passage, a crank arm on said shaft having a link connecting with the crank arm on said bracket, a cutter for the head end of the wrapper carried by said bracket, and means for reciprocating said slide to move the cutter thereon into and out of cooperative relation with the other cutter, and means for automatically swinging said jaws on their pivots to open and close the cluster of rolls carried thereby, and for simultaneously rocking said bracket.

107. In a cigar machine, a cluster of wrapper-applying rolls within which the bunch is rotated, two pairs of jaws by which said rolls are carried, a rock shaft to which two of said jaws are secured, a sleeve loosely mounted on said shaft to which the other jaws are secured, a bracket mounted for rocking movement transversely of said cluster of rolls at the head end thereof, the said bracket being provided with a crank arm, and a bearing sleeve and having a cylindrical passage therethrough, a paste receptacle communicating with said passage, a crank arm on said shaft having a link connecting with the crank arm on said bracket, a cutter for the head end of the wrapper carried by said bracket, and means for reciprocating said slide to move the cutter thereon into and out of cooperative relation with the other cutter, and means for automatically swinging said jaws on their pivots to open and close the cluster of rolls carried thereby, and for simultaneously rocking said bracket.

- carried by said bracket and located at the head end of the bunch, a slide mounted on said bracket having an elongated transversely extending slot therein, a cutter secured to said slide coöperating with the cutter on said bracket, a plunger carried by said slide and adapted to fit within said passage, a rotary shaft extending through the bearing sleeve on said bracket, having 5 a crank pin or projection thereon which fits within the elongated slot in said slide, means for rotating the latter shaft, and means for automatically rocking said rock shaft and the sleeve thereon in opposite directions to 10 swing said jaws to open and close the cluster of rolls carried thereby and to rock said bracket.
107. In a cigar machine, a cluster of wrapper-applying rolls within which the bunch is rotated, two pairs of jaws by which 20 said rolls are carried, a rock shaft to which two of said jaws are secured, a sleeve loosely mounted on said shaft to which the other jaws are secured, a bracket mounted for 25 rocking movement transversely of said cluster of rolls at the head end thereof, the said bracket being provided with a crank arm and a bearing sleeve, a crank arm on said rock shaft having a link connection with the 30 crank arm on said bracket, a cutter for the head end of the wrapper carried by said bracket and located at the head end of the bunch, a slide mounted on said bracket and having a transversely extending elongated 35 slot therein, a cutter secured to said slide, coöperating with the cutter on said bracket, a rotary shaft extending through the bearing sleeve on said bracket having a crank pin or projection thereon which fits within 40 the elongated slot in said slide, a gear wheel having a cam groove or race therein, a system of gearing between said gear wheel and said rotary shaft including a clutch, one member of said clutch being a pinion loosely 45 mounted on said rotary shaft and having notches therein, and the other member of said clutch being a sleeve having a spline connection with said rotary shaft and having a pin thereon adapted to fit within one 50 or the other of the notches in said pinion, a rocking lever having a fork on one arm thereof which fits within a groove in the latter clutch member, a second lever having a projection on one arm thereof fitting within 55 the cam groove or race in said gear wheel, the other arm thereof being adapted to engage said rocking lever for throwing said clutch members into locking engagement with each other, means to operate said rocking 60 lever in the reverse direction to disengage the clutch, and means for automatically rocking said rock shaft and the sleeve thereon in opposite directions to swing the said jaws to open and close the cluster of rolls carried thereby and to rock said bracket. 65
108. In a cigar machine, a cluster of wrapper-applying rolls within which the bunch is rotated, a wrapper support on one side of said rolls, a wrapper carrier on the opposite side of said rolls, means for automatically raising said carrier to a point above said rolls to deposit the projecting end of the wrapper onto said support and for returning said carrier to its normal depressed 70 position to draw the wrapper around the upper of said rolls, and a tucking needle adapted to engage the wrapper while on said support to force the same down within said rolls into contact with the bunch. 75
109. In a cigar machine, a cluster of wrapper-applying rolls within which the bunch is rotated, a fixed suction plate constituting a wrapper support on one side of 80 said rolls, a wrapper carrier on the opposite side of said rolls having a suction plate at its delivery end over which the wrapper passes, means for automatically raising said carrier to a point above said rolls to deposit the projecting end of the wrapper upon said fixed 85 suction plate and for returning said carrier to its normal depressed position to draw the wrapper over the upper of said rolls, and a tucking needle adapted to engage the wrapper while on said fixed suction plate to 90 force the same down within said rolls into contact with the bunch. 95
110. In a cigar machine, a cluster of wrapper-applying rolls within which the bunch is rotated, means for delivering a 100 wrapper thereto, a tucking needle, means for projecting and flexing said needle to engage the end of the wrapper to force the same down within said rolls into contact with said bunch, and means for automatically withdrawing said needle from the bunch when more than one complete rotation of the same has been effected. 105
111. In a cigar machine, a cluster of wrapper-applying rolls within which the bunch is rotated, means for delivering a 110 wrapper thereto, a tucking needle adapted to engage the end of the wrapper to force the same down within said rolls into contact with said bunch, means for automatically withdrawing said needle from the bunch when more than one complete rotation of the same has been effected, and means for automatically re-inserting the needle 115 into the bunch at the center of the tuck end thereof. 120
112. In a cigar machine, a cluster of wrapper-applying rolls within which the bunch is rotated, means for delivering a 120 wrapper thereto, a spring tucking needle, means for automatically bending said needle to move the free end thereof to a point outside the wrapper, means for automatically

- releasing the pressure on said needle to enable the same to force the end of the wrapper down within said rolls into contact with said bunch, and means for automatically moving said needle longitudinally to withdraw the same from the bunch when said bunch has made more than one complete rotation.
113. In a cigar machine, a cluster of wrapper-applying rolls within which the bunch is rotated, means for delivering a wrapper thereto, a spring tucking needle, means for automatically bending said needle to move the free end thereof to a point outside the wrapper, means for automatically releasing the pressure on said needle to enable the same to force the end of the wrapper down within said rolls into contact with said bunch, means for automatically moving said needle longitudinally to withdraw the same from the bunch when said bunch has made more than one complete rotation, and means for automatically reinserting said needle into the bunch at the center of the tuck end thereof.
114. In a cigar machine, a cluster of wrapper-applying rolls within which the bunch is rotated, means for feeding a wrapper thereto, a tubular part or sleeve in line with the bunch in said rolls, a spring tucking needle extending through said sleeve and adapted to engage the projecting end of the wrapper to force the same down within said rolls into contact with the bunch, a forked lever adapted to engage said needle for bending the same, a link connecting said lever with said sleeve, means for automatically moving said sleeve independently of said needle to cause the engagement of said lever with said needle to bend the same, and means for automatically moving said needle longitudinally in said sleeve.
115. In a cigar machine, a cluster of wrapper-applying rolls within which the bunch is rotated having pinions thereon by which they are turned, means for delivering a wrapper thereto, a tubular shaft located in line with the bunch and having a pinion thereon meshing with the pinions on said rolls, means for rotating said shaft, a longitudinally movable tubular part or sleeve within said shaft, a spring tucking needle extending through said sleeve and adapted to engage the projecting end of the wrapper to force the same down within said rolls into contact with the bunch, a forked lever fulcrumed upon a stationary part and adapted to engage said needle for bending the same, connections between said lever and said sleeve, means for automatically moving said sleeve longitudinally to cause the engagement of said lever with said needle to bend the latter, and means for automatically moving said needle longitudinally within said sleeve.
116. In a cigar machine, a cluster of wrapper-applying rolls within which the bunch is rotated, two pairs of pivoted jaws by which said rolls are carried, means for feeding and delivering a wrapper to the bunch within said rolls, a rotary shaft mounted for longitudinal movement opposite the head end of the bunch, a shaping and polishing cup on the end of said shaft, a rotary gear wheel having a serrated flange thereon against which said shaft bears, a spring for holding said shaft in engagement with said flange, a pinion rotated by said gear wheel, and a spline connection between said pinion and said shaft, whereby said shaft is caused to rotate and to approach and recede from the bunch to move the cup thereon into and out of contact with the tip end thereof.
117. In a cigar machine, a cluster of wrapper-applying rolls within which the bunch is rotated and by which the bunch is supported, means for automatically opening said rolls after the wrapper has been applied to the bunch, an independent support for the bunch after the rolls have opened, and a shaping and polishing cup for the tip of the cigar automatically thrown into operation when said rolls are opened.
118. In a cigar machine, a cluster of wrapper-applying rolls within which the bunch is rotated and by which the bunch is supported, means for automatically opening said rolls after the wrapper has been applied to the bunch, a temporary independent support for the bunch after the rolls have opened, and a cutter for the tuck end of the bunch automatically thrown into operation when said jaws are opened.
119. In a cigar machine, a cluster of wrapper-applying rolls within which the bunch is rotated and by which the bunch is supported, a needle adapted to be introduced into the tuck end of the bunch while in said rolls, means for automatically opening said rolls when the wrapper has been applied to the bunch, a support for the bunch independent of said rolls, means for automatically moving said support into operative position when said rolls have opened, means for automatically withdrawing said needle from the bunch, a cutter for the tuck end of the bunch, and means for automatically operating the same as said needle is withdrawn.
120. In a cigar machine, a cluster of wrapper-applying rolls within which the bunch is rotated and by which the bunch is supported, a needle adapted to be introduced into the tuck end of the bunch while in said rolls, means for automatically opening said rolls when the wrapper has been applied to the bunch, a support for the bunch independent of said rolls, means for automatically moving said support into operative

position when said rolls have opened, a polishing cup for the tip of the bunch automatically thrown into operation when said rolls have opened, means for automatically withdrawing said needle from the bunch, and means for automatically releasing said support from the bunch.

121. In a cigar machine, a cluster of wrapper-applying rolls within which the bunch is rotated and by which the bunch is supported, a needle adapted to be introduced into the tuck end of the bunch while in said rolls, means for automatically opening said rolls when the wrapper has been applied to the bunch, a support for the bunch independent of said rolls, means for automatically moving said support into operative position when said rolls have opened, a polishing cup for the tip of the bunch automatically thrown into operation when said rolls have opened, means for automatically withdrawing the needle from the bunch, a cutter for the tuck end of the bunch, means for automatically actuating the same as said needle is withdrawn, and means for automatically disengaging said support from the bunch.

122. In a cigar machine, a cluster of wrapper-applying rolls within which the bunch is rotated, means for automatically opening said rolls when the wrapper has been applied to the bunch, a gripper located beneath the bunch in said rolls, a cutter for the tuck end of the bunch also located beneath the bunch within said rolls, and means for automatically elevating said gripper and said cutter to cause the engagement of the former with the bunch when the said rolls have separated and to simultaneously actuate the latter to cut the tuck end of the bunch.

123. In a cigar machine, a cluster of wrapper-applying rolls within which the bunch is rotated and by which the bunch is supported, means for automatically opening said rolls when the wrapper has been applied to the bunch, a gripper for the support of the bunch when said rolls are open, comprising a pair of pivoted jaws, a rod, and link connections between said rod and said jaws, a cutter for the tuck end of the bunch comprising a pair of pivoted jaws, a rod and a link connection between said rod and said jaws, means for automatically raising said gripper and cutter bodily toward the bunch as said rolls are opened, and means for subsequently moving said rods independently of the jaws of said gripper and cutter to move said jaws on their pivots.

124. In a cigar machine, a cluster of wrapper-applying rolls within which the bunch is rotated, means for automatically opening said rolls when the wrapper has been applied to the bunch, a gripper for the support of the bunch when said rolls are

open, comprising a pair of pivoted jaws, a rod, and a link connection between said rod and said jaws, a cutter for the tuck end of the bunch comprising a pair of pivoted jaws, a rod, and a link connection between said rod and said jaws, a vertically reciprocating slide having lateral arms thereon through which said rods freely pass, a spring surrounding the rod of said gripper engaging the upper side of one arm on said slide and a shoulder on the gripper rod, a second slide on which the first is mounted, the said second slide being mounted in a stationary part of the frame and having a stop or projection thereon adapted to engage said stationary part during its upward movement, a lateral arm on said second slide through which the rod of said cutter passes, a head or shoulder on the lower end of the latter rod, and a spring surrounding the latter rod engaging said head and the lower side of the arm on said second slide.

125. In a cigar machine, a cluster of wrapper-applying rolls within which the bunch is rotated, means for automatically opening said rolls when the wrapper has been applied to the bunch, a longitudinally movable needle adapted to be introduced into the tuck end of the bunch within said rolls, a gripper located beneath the bunch in said rolls, a cutter for the tuck end of the bunch also located beneath the bunch in said rolls, means for automatically elevating said gripper and said cutter to cause the engagement of the former with the bunch and to bring said cutter to a point opposite the tuck end of the bunch when said rolls have separated, the said gripper and the said needle constituting at this time a support for the bunch, means for automatically withdrawing said needle from the bunch, and means for actuating said cutter to clip the bunch when said needle has been withdrawn therefrom.

126. In a cigar machine, a cluster of wrapper-applying rolls within which the bunch is rotated, a gripper for temporarily supporting the completed cigar after said rolls have opened, and means carried by said gripper for branding the cigar thus held.

127. In a cigar machine, a cluster of wrapper-applying rolls within which the bunch is rotated, a gripper for temporarily supporting the completed cigar after said rolls have opened, the said gripper comprising a pair of pivoted jaws adapted to embrace the cigar, and type projecting inwardly beyond the inner face of one of said jaws for branding the cigar when said jaws are closed thereon.

128. In a cigar machine, a wrapper feeding means embodying a movable perforated device, means for applying suction to and through said device, and wrapper applying

- mechanism, the movable device having suction cut off therefrom when the perforations thereof reach the feeding extremity of the said wrapper feeding means and from the portion of the wrapper on the movable device at said feeding extremity to relieve the strain from the wrapper and project the latter into the wrapper applying mechanism for application to a bunch.
130. In a cigar machine, a wrapper-feeding means, wrapper-applying mechanism, and a suction device between the said means and mechanism for holding a wrapper raut after it leaves the said wrapper feeding means.
131. In a cigar machine, a support, a wrapper-feeding means movable thereon, wrapper-applying mechanism, and suction means for supporting a wrapper when leaving the feeding means and passing to the wrapper-applying mechanism.
132. In a cigar machine, a support, a wrapper-feeding means movable thereon and operative to project a wrapper therefrom, wrapper-applying mechanism into which the wrapper is projected, and automatically controlled tension exerting means for the projected portion of the wrapper disposed between the said means and mechanism.
133. In a cigar machine, wrapper-applying mechanism, means for polishing and burnishing the tip end of a cigar, gripping means for preventing a cigar from shifting its position while the tip is being finished, means for cutting the thick end of the cigar, and means for releasing the gripping means to permit discharge of the finished cigar.
134. In a cigar machine, wrapper-applying mechanism, means for supporting a cigar when released by the wrapper-applying mechanism, tip-polishing and shaping means, means for holding the cigar against endwise movement while the tip is being finished, means for cutting the thick end of the cigar, mechanism for withdrawing the supporting means from the cigar while the thick end is being cut, and mechanism for actuating the holding and cutting means to permit discharge of the finished cigar.
135. In a cigar machine, a reciprocatory filler table including cutting mechanism, oscillatory bunch forming mechanism, means for depositing fillers and binder thereon, means for holding and laterally compressing a bunch, and means for ejecting the bunch from the holder.
136. In a cigar machine, bunch-conveying and shaping mechanism, means for exerting pressure on the bunches within the convey-
- ing and shaping mechanism, means for automatically applying and releasing said pressure exerting means, wrapper-applying mechanism, and oscillatory means for individually removing the bunches from the conveyer and directly transferring them to the wrapper-applying mechanism.
137. In a cigar machine, the combination with wrapper-applying mechanism, of means for delivering a wrapper thereto and provided with movable means for projecting a wrapper therefrom, and means for automatically varying the speed of feed of said wrapper-delivering means to compensate for variations in the diameter of the bunch to which the same is applied.
138. In a cigar machine, the combination with wrapper-applying mechanism, of means for delivering a wrapper thereto and provided with movable means for projecting a wrapper therefrom, means for automatically varying the speed of delivery of said wrapper to compensate for variations in the diameter of the bunch to which the same is applied, and means for automatically varying the angle of presentation of the wrapper to the wrapper-applying mechanism.
139. In a cigar machine, the combination with wrapper applying mechanism, of a wrapper-carrier movable longitudinally of said wrapper-applying mechanism, rollers supported by the carrier, a traveling apron constituting a wrapper-feeder passing around said rollers and deriving its motion toward said wrapper-applying mechanism therefrom, means for automatically imparting to said rollers a variable speed of rotation, and means for simultaneously imparting to said carrier a variable longitudinal movement.
140. In a cigar machine, the combination with a main drive shaft having a cam thereon, and wrapper-applying mechanism, of a wrapper-carrier movable longitudinally of said mechanism, a wrapper-feeder mounted on said carrier and movable toward said wrapper-applying mechanism, and connections between said cam and said carrier for imparting to the latter a variable movement in the direction of the length of the wrapper-applying mechanism.
141. In a cigar machine, a suction box having an opening in one wall thereof, wires arranged across said opening with their outer edges in the same plane with the outer surface of the wall of said suction box in which said opening is formed, and a perforated wrapper-feeder movable over said suction box for delivering wrappers to the wrapper-applying mechanism.
142. In a cigar machine, a suction box having an opening in one wall thereof, wires arranged across said opening with their outer edges in the same plane with the outer surface of the wall of said suction box in

which said opening is formed, fixed supports for said wires extending transversely of the same, and a perforated wrapper-feeder movable over said suction box for delivering 5 wrappers to the wrapper-applying mechanism.

143. In a cigar machine, a suction box having an opening in one wall thereof, wires arranged across said opening with their 10 outer edges in the same plane with the outer surface of the wall of said suction box in which said opening is formed, a series of slats secured within said suction box extending transversely of said wires and serving 15 as supports therefor, and a perforated wrapper-feeder movable over said suction box for delivering wrappers to the wrapper-applying mechanism.

144. A cigar machine embodying the following elements operating automatically and sequentially and in the order named, a binder-carrier including suction means, a movable table having a removable filler receptacle therein and including cutting mechanism for trimming the ends of the filler, a bunch-making mechanism having a belt thereon, means for operating the binder-carrier to deliver a binder on the belt, means for depositing a filler over the binder and 20 for forming a pocket in the belt, means for wrapping the binder around the filler and making a bunch, means for holding and laterally compressing a bunch, bunch-shaping and conveying mechanism, means for moving the bunch-holding and compressing mechanism to a position over the shaping and conveying mechanism, means for holding the bunch in the shaping and compressing mechanism, means for transferring motion 25 to the shaping and compressing mechanism, means for releasing the bunch within the shaping and compressing mechanism, means for trimming the terminals of the bunch while being so engaged, wrapper-applying mechanism embodying a plurality of 30 pivotally supported rolls, means for transferring the bunch from the shaping and conveying mechanism to the wrapper-applying mechanism, means for cutting a wrapper to the desired shape, wrapper-carrying mechanism including suction means, and a wrapper-feeder for feeding the wrapper-carrying mechanism and feeder at variable angles and 35 variable rates of speed and in proper proportion to the bunch to correspond to the various diameters thereof while being revolved, means for transferring a wrapper from the wrapper-cutting mechanism to the 40 wrapper-feeding and wrapper-applying mechanism, means for tucking the wrapper around the tuck end of the bunch, means for applying paste to the head end of the bunch and wrapper, means for nicking and cutting the head end of the wrapper while being 45 wrapped around the bunch, means for open-

ing and closing the wrapper-applying rolls, means for supporting the bunch when it is released from the wrapper-applying mechanism, head polishing and shaping means, means for firmly holding the bunch against 50 movement under operation of the polishing and shaping means, means coacting with the supporting means for cutting the tuck end of the bunch, means for withdrawing the supporting means while the tuck end of the 55 bunch is being cut, and means for releasing the holding means after the tuck has been cut to release the finished cigar.

145. In a cigar machine, the combination with wrapper applying mechanism, of a carrier movable longitudinally of said wrapper applying mechanism, a wrapper feeder supported by said carrier, means for moving said feeder toward said wrapper applying mechanism, and means for varying the angle 85 of said feeder with respect to said wrapper applying mechanism during the longitudinal movement of said carrier.

146. In a cigar machine, the combination with wrapper applying rolls, one of which 90 extends beyond the others, a fixed part at the head end of the shorter rolls, a paste delivery pipe extending through said fixed part, a paste receptacle communicating with said pipe, a plunger in said pipe, means for 95 adjusting the stroke of the plunger, and means for automatically reciprocating said plunger.

147. In a cigar machine, the combination with wrapper-applying rolls, one of which 100 extends beyond the others, a fixed part at the head end of the shorter of said rolls, a paste delivery pipe extending through said fixed part, a paste receptacle, a supply pipe leading from said paste receptacle to said 105 delivery pipe, a slide, means for automatically reciprocating said slide, and a plunger secured to said slide located within said delivery pipe and adapted to be reciprocated by said slide back and forth across the point 110 of intersection of said supply pipe with said delivery pipe.

148. In an organized cigar machine, the combination of mechanism for feeding a filler to a binder, means for rolling the filler 115 in the binder, means for initially shaping and compressing the bound filler to form bunches, bunch wrapping mechanism, means for lifting the bunches from the shaping and compressing means and individually transferring them to said wrapper mechanism, and means for feeding a wrapper to the bound filler.

149. In a cigar wrapping machine, the combination with wrapper applying mechanism, wrapper-shaping means co-operating therewith, wrapper-feeding means, and means for disposing the wrapper into 125 wrapper shaping contact with the wrapper shaping means.

150. In a cigar wrapping machine, the combination with wrapping mechanism, of means for feeding and presenting a wrapper thereto, an element shaped to conform to the shape of the bunch to be wrapped and on which the wrapper is disposed, and means for actuating the wrapper-feeding mechanism to bring a wrapper into wrapper-shaping contact with said wrapper-shaping element. 45
151. In a cigar wrapping machine, the combination with wrapping mechanism, of means for presenting a wrapper thereto including means for bodily moving and projecting the wrapper from said presenting means to said wrapping mechanism, and means for varying the angular relation between said wrapping mechanism and said presenting means. 50
152. The combination with a wrapping mechanism, of means for bodily moving and feeding wrappers thereinto, a bunch support constructed to sustain a plurality of bunches, means for transferring bunches from the support to the wrapping mechanism, and means for operating the support to bring the bunches successively within the range of action and individual delivery of the transferring means. 55
153. The combination with a wrapping mechanism, of means for bodily moving and feeding wrappers thereinto, a flexible bunch support constructed to sustain a plurality of bunches, means for individually transferring bunches from the support to the wrapping mechanism, and means for operating the support to bring the bunches successively within the range of action of the transferring means. 60
154. In a cigar machine, the combination with a bunch forming mechanism, of means for supplying filler material and binders thereto, a wrapping mechanism, means for transferring the bunches from the bunch forming mechanism to the wrapping mechanism, means for supplying wrappers to the wrapping mechanism, and finishing means operating on the cigar after it is completed by and held in the wrapping mechanism. 65
155. In a cigar machine, the combination with a bunch forming mechanism, of means for supplying filler material and binders thereto, a wrapping mechanism, means for transferring bunches from the bunch forming mechanism to the wrapping mechanism, means for forming and supplying wrappers to the wrapping mechanism, and finishing means operating on the cigar after it is completed by and held in the wrapping mechanism. 70
156. In a cigar machine, a movable carrier, wrapper-feeder mechanism shiftably mounted on and movable independently of the said carrier, and a wrapper-feeder actuator and controller operatively connected with the wrapper feeder to move the latter and feed the wrapper in proportion to the thickness of the bunch to which the wrapper is applied. 75
157. In a cigar machine, wrapper applying mechanism, a carrier, a wrapper-feeder supported thereby provided with means for bodily moving and projecting a wrapper therefrom, means for presenting the feeder at various angles to the wrapper applying mechanism independently of the carrier, and means for causing the feeder to resume its normal position on the carrier. 80

In testimony whereof I have hereunto set my hand in presence of two subscribing witnesses.

JOSEPH D. LACROIX.
